TELEPHONE SYSTEM

Thomas F. Crocker and Howard H. Smith, Chicago, Ill., assignors to Automatic Electric Laboratories, Inc., a corporation of Delaware

Application February 16, 1942, Serial No. 431,076

44 Claims. (Cl. 179—41)

The present invention relates to telephone systems and more particularly to conference communication networks.

It is an object of the present invention to provide a conference telephone system comprising an improved amplifier network, whereby the system may serve a relatively large number of stations.

Another object of the invention is to provide a conference telephone system comprising an improved impedance balancing network, whereby the system may serve a number of lines having impedances varying over a considerable range.

A further object of the invention is to provide in a conference telephone system, an improved arrangement for preselecting different combinations of the stations served thereby as called stations and then for signaling only the preselected combination of stations when a call is initiated thereon.

A still further object of the invention is to provide in a conference telephone system including an operator position, an improved arrangement for rendering complete supervision of the system to the operator at the operator position.

Further features of the invention pertain to the particular arrangement of the circuit elements thereof, whereby the above-outlined and additional operating features are attained.

The invention, both as to its organization and method of operation, together with further objects and advantages thereof, will best be understood by reference to the following specification taken in connection with the accompanying drawings, in which Figure 1 illustrates the general arrangement of a telephone system embodying the present invention; Figs. 2 to 9, inclusive, taken together, illustrate the details of the system having incorporated therein the features of the invention, as briefly outlined above; and Fig. 10 illustrates the mode of combining Figs. 2 to 9, inclusive, in order to form a unified system.

Description of the apparatus incorporated in the telephone system

Referring now more particularly to Fig. 1 of the drawings the telephone system there illustrated comprises a central office serving three areas X, Y and Z, the area X being adjacent the central office, the area Y being somewhat removed from the central office and the area Z being considerably removed from the central office. The area X serves a number of telephone stations arranged in pairs 1XA, 1XB and 2XA, 2XB etc.; the area Y serves a number of tele-

phone stations arranged in pairs 1YA, 1YB and 2YA, 2YB etc.; and the area Z serves a number of telephone stations arranged in pairs 1ZA, 1ZB and 2ZA, 2ZB etc. The central office comprises a number of pairs of line circuits 105, 106 etc. individual to the pairs of telephone stations 1XA, 1XB etc., each telephone station being connected by a telephone line to the line circuit individual thereto. More particularly, the telephone stations 1XA, 1XB, 2XA and 2XB are individually connected by the respective telephone lines 101, 102, 103 and 104 to the respective line circuits 105, 106, 107 and 108; while the telephone stations 1YA, 1YB, 2YA and 2YB are individually connected by the respective telephone lines 111, 112, 113 and 114 to the respective line circuits 115, 116, 117 and 118. Finally the telephone stations 1ZA, 1ZB, 2ZA and 2ZB are individually connected by the respective telephone lines 121, 122, 123 and 124 and respective adapter circuits 135, 136, 137 and 138 to the respective line circuits 125, 126, 127 and 128.

At this point it is noted that each of the adapter circuits comprises two portions respectively disposed in the area Z and in the central office and connected together by a trunk line. More particularly, the two portions of the respective adapter circuits 135, 136, 137 and 138 are connected together by the trunk lines 131, 132, 133 and 134.

The central office comprises a pair of booster transformers 141 and 142, a simulating impedance network 151 and a paired operator position 152, an amplifier network 171 and a test desk 161. The amplifier network 171 is of the well-known type 21 comprising an A loop and a B loop. The A loop of the amplifier network 171 includes an operative connection to the simulating impedance network 151, an operative connection to one-half of the number of line circuits individual to the telephone stations in the area Z, an operative connection to the booster transformer 141 and an operative connection to one-half of the number of line circuits individual to the telephone stations in the area X; while the B loop of the amplifier network 171 includes an operative connection to the operator position 152, an operative connection to the other half of the number of line circuits individual to the telephone stations in the area Z, an operative connection to the booster transformer 142 and an operative connection to the other half of the number of line circuits individual to the telephone stations in the area X. Finally the booster transformer 141 includes an operative connection to one-half of

the number of line circuits individual to the telephone stations in the area Y; while the booster transformer 142 includes an operative connection to the other half of the number of line circuits individual to the telephone stations in the area Y.

In other words, the telephone stations 1XA, 2XA etc., in the area X, the telephone stations 1YA, 2YA etc., in the area Y, and the telephone stations 1ZA, 2ZA etc., in the area Z, are operatively connected to the A loop of the amplifier network 171; while the telephone stations 1XB, 2XB etc., in the area X, the telephone stations 1YB, 2YB etc., in the area Y, and the telephone stations 1ZB, 2ZB etc., in the area Z, are operatively connected to the B loop of the amplifier network 171. Finally the simulating impedance network 151 is operatively connected to the A loop of the amplifier network 171; while the operator position 152 is operatively connected to the B loop of the amplifier network 171. In view of the facts that the telephone stations in each area are arranged in pairs and respectively operatively connected to the two loops of the amplifier network 171, and the simulating impedance network 151 and the operator position 152 are paired and respectively operatively connected to the two loops of the amplifier network 171, the impedances of the two loops of the amplifier network 171 are normally balanced in a manner more fully explained hereinafter.

More particularly, the amplifier network 171 comprises two repeaters 200 and 205, a transmission equalizer circuit 210, a transformer 220, a potentiometer 225, two amplifier tubes 230 and 240 and a control network connected and arranged in a manner more fully explained hereinafter.

Preferably, each of the line circuits is substantially identical to the line circuit 126 individual to the telephone station 1ZB, in the area Z, which comprises, as best shown in Figs. 4, 5 and 6, a repeater 400, a line pad 430, a simulating pad 410 and a relay group, including a line relay R405, a hold relay R440, an answer relay R450, a pad switching relay R460, a ring cutoff relay R510, a release relay R520, a ring relay R530, a lockout relay R540, a call relay R550, a cutoff relay R560 and a test relay R570. Also the line circuit 126 comprises three test jacks J420, J576 and J577 which are utilized for a purpose more fully explained hereinafter, as well as a control network more fully described subsequently.

The various line circuits are directly connected to the telephone lines extending to the telephone stations in the areas X and Y and to the adapter circuits individual to the telephone stations in the area Z, as previously noted and as clearly indicated in Fig. 6. The line circuit 126 illustrated is individual to the telephone station 1ZB in the area Z; accordingly the adapter circuit 136 is interposed between the line circuit 126 and the telephone line 122 extending to the telephone station 1ZB, as previously noted.

Preferably, each of the adapter circuits is identical to the adapter circuit 136 which comprises, as shown in Fig. 6, two repeaters 640 and 650 respectively disposed in the central office and in the area Z, a simplex relay R620 and a test relay R630 disposed in the central office, and a control network connected and arranged in a manner more fully described hereinafter.

The simulating impedance network 151 comprises, as shown in Fig. 3, a repeater 300, an impedance element 1305, a simulating pad 310, a

test jack J320 and a control network connected and arranged in a manner more fully described hereinafter.

The operator position 152 comprises, as shown in Figs. 7, 8 and 9, two repeaters 700 and 765, a line pad 730, a simulating pad 710, two impedance elements 1705 and 1874 and a relay group, including a pad switching relay R770, an answer relay R830, a cutoff relay R840, an amplifier start relay R850, a supply relay R860, an alarm relay R870, a call relay R880 and three group ring start relays R850, R960 and R970. Also the operator position 152 comprises a receiver 751, a transmitter 759, a transmitter shunt key K758, a hook switch S760 and a receiver amplifier network, including a transformer 735, an amplifier tube 744 of the type 1H4G, a repeater 740, a potentiometer 743, a receiver transfer key K750 and a control network connected and arranged in a manner more fully described hereinafter. Further the operator position 152 comprises a control key set including a common talk key K800, a common ring key K805, a common start key K810, a common test key K820, a plurality of individual ring control keys K827 etc., respectively corresponding to the line circuits 126 etc., a plurality of individual talk keys K910 etc., respectively corresponding to the line circuits 126 etc., a plurality of individual ring start keys K920 etc., respectively corresponding to the line circuits 126 etc., three group ring start keys K941, K942 and K943, respectively corresponding to three groups of the line circuits 126 etc., and an all-groups ring start key K944. Finally the operator position 152 comprises a set of control lamps, including a common answer pilot lamp L820, a plurality of individual answer lamps L817 etc., respectively corresponding to the line circuits 126 etc., a plurality of individual line lockout lamps L819 etc., respectively corresponding to the line circuits 126 etc., a plurality of individual ring lamps L931 etc., respectively corresponding to the line circuits 126 etc., and a plurality of individual call lamps L932 etc., respectively corresponding to the line circuits 126 etc. Finally the operator position 152 comprises a control network connected and arranged in a manner more fully described hereinafter.

Each of the telephone stations 1XA etc. comprises conventional telephone station equipment including a receiver, a transmitter, a hook switch, a ringer and a control network. Also the test desk 161 indicated in Fig. 6 comprises conventional test desk equipment.

The amplifier network 171 comprises, as shown in Fig. 2, a control network including an amplifier start slave relay R260, a filament alarm relay R270, a plate alarm relay R280, a monitor jack J290 and an alarm lamp L291. Each of the amplifier tubes 230 and 240 is of the type 25L6G comprising a plate, a cathode, a cathode heater, a screen grid and a control electrode. The cathode heaters 235 and 245 of the respective amplifier tubes 230 and 240 are normally connected in series circuit relation with the winding of the filament alarm relay R270, whereby the latter relay is normally retained in its operated position and the cathodes 232 and 242 of the respective amplifier tubes 230 and 240 are retained in electron emitting condition. Also the amplifier network 171 comprises a cathode biasing circuit, including the resistor 253 and the condensers 254 and 255, connected between the cathodes 232 and

242 and the control electrodes 233 and 243 of the respective amplifier tubes 230 and 240.

The repeater 200 comprises a primary winding 201 connected in the plate circuit of the amplifier tubes 230 and 240 and a secondary winding 202 connected to ground potential and to a common point in the A loop and the B loop. The repeater 205 comprises four windings 206, 207, 208 and 209, the windings 206 and 207 being respectively connected to the opposite ends of the A loop and the B loop, to the windings 208 and 209 and to the opposite terminals of the transmission equalizer circuit 210. Also the windings 208 and 209 are connected together and to ground potential. The transmission equalizer circuit 210 comprises two impedance elements 211 and 212, a resistor 213 and two condensers 214 and 215, and is adapted to insure substantially uniform response of the amplifier tubes 230 and 240 over the audible frequency band. Also the transmission equalizer circuit 210 is connected to the primary winding 221 of the transformer 220, the secondary winding 222 of the transformer 220 being connected to the potentiometer 225. Finally the potentiometer 225 is connected by way of two resistors 251 and 252 to the control electrodes 234 and 244 of the respective amplifier tubes 230 and 240. Further it is noted that the output circuit of the tubes 230 and 240 includes a source of anode potential having its negative terminal connected to the upper terminal of the relay R280 and its positive terminal connected to ground.

Considering now the normal condition of the amplifier network 171 and the two associated loops, it is pointed out that the amplifier start slave relay R260 normally occupies its restored position, whereby the two parallel connected amplifier tubes 230 and 240 are normally nonconductive. Also, normally, the receiver at each telephone station occupies its on-hook position, thereby to interrupt the connection by way of the associated telephone line to the individually associated line circuit. Similarly, at the operator position 152, the receiver 151 occupies its on-hook position with respect to the associated hook switch S760, whereby the equipment at the operator position 152 normally occupies its released condition. Accordingly the repeaters 400 etc. in the various line circuits 126 etc. are normally unloaded; and the repeater 700 in the operator position 152 and the repeater 300 in the simulating impedance network 151 are normally unloaded. At this time the A loop extends from ground by way of the secondary winding 202 of the repeater 200, the contacts 323 of the test jack J320, the primary windings 392 and 391 of the repeater 300, the contacts 322 of the test jack J320, the primary windings of repeaters in line circuits not shown, the primary winding of the repeater in the line circuit 125, the primary winding of the booster transformer 141, the primary windings of repeaters in line circuits not shown, the primary winding of the repeater in the line circuit 195 and the windings 206 and 208 of the repeater 205 to ground; and the B loop extends from ground by way of the secondary winding 202 of the repeater 200, the contacts 723 of the test jack J720, the primary windings 702 and 701 of the repeater 700, the contacts 722 of the test jack J720, the primary windings of repeaters in line circuits not shown, the contacts 423 of the test jack J420, the primary windings 402 and 401 of the repeater 400 in the line circuit 126, the contacts 422 of the test jack J420, the primary winding of the booster

transformer 142, the primary windings of repeaters in line circuits not shown, the primary winding of the repeater in the line circuit 106, and the windings 207 and 209 of the repeater 205 to ground. In view of the facts that the A loop includes the unloaded repeater 300 in the simulating impedance network 151 and a fixed number of unloaded repeaters in a corresponding number of line circuits, and the B loop includes the unloaded repeater 700 in the operator position 152 and a fixed number of unloaded repeaters in a corresponding number of line circuits, wherein the fixed numbers are the same, the impedances of the two loops are identical. Accordingly the two loops are balanced with respect to the amplifier network 171; and in the event the two amplifier tubes 230 and 240 were rendered conductive the two loops would conduct balanced currents. Hence, a stable condition would exist in the repeater 205 preventing singing of the amplifier network 171 with respect to the two associated loops.

As previously noted, the line circuit 125 individual to the telephone station 1ZA, in area Z, and the line circuit 126 individual to the telephone station 1ZB, in area Z, are respectively arranged in the A loop and in the B loop and are balanced with respect to each other. More particularly, when the repeater in the line circuit 125 and the repeater 400 in the line circuit 126 are either unloaded or loaded the A loop and the B loop are balanced with respect to the amplifier network 171. This is accomplished by balancing the impedance of the primary winding of the repeater in the line circuit 125 with respect to the impedance of the primary winding of the repeater 400 in the line circuit 126 when the repeaters mentioned are unloaded, and by balancing the impedance connected to the secondary winding of the repeater in the line circuit 125 with respect to the impedance connected to the secondary winding of the repeater 400 in the line circuit 126 when the repeaters mentioned are loaded. More particularly, in the line circuit 126, the effective impedance produced by the line pad 430, the secondary windings 403 and 404 of the repeater 400, the upper and lower windings of the line relay R405, the adapter circuit 136, the telephone line 122 extending to the telephone station 1ZB, in area Z, and the station equipment at the telephone station 1ZB is fixed at a given value when the repeater 400 is loaded by correctly adjusting the line pad 430. Similarly, in the line circuit 125, the effective impedance produced by the line pad, the secondary windings of the repeater, the upper and lower windings of the line relay, the adapter circuit 135, the telephone line 121 extending to the telephone station 1ZA, in area Z, and the station equipment at the telephone station 1ZA is fixed at a given value when the repeater is loaded by correctly adjusting the line pad. Thus the effective impedances presented by the line circuits 126 and 125 to the amplifier network 171 are substantially equal throughout the range of frequencies which are effectively amplified.

Also, in the line circuit 126, the impedance of the simulating pad 410 is initially set to equal the effective impedances of the line pad 430, the adapter circuit 136, the telephone line 122 extending to the telephone station 1ZB, in area Z, and the telephone equipment at the telephone station 1ZB, whereby the repeater 400 is equally loaded by the simulating pad 410 or the combination of the other impedances mentioned,

including the telephone equipment at the telephone station 1ZB. Similarly, in the line circuit 125, the impedance of the simulating pad is initially set to equal the effective impedances of the line pad, the adapter circuit 135, the telephone line 121 extending to the telephone station 1ZA, in area Z, and the telephone equipment at the telephone station 1ZA, whereby the repeater is equally loaded by the simulating pad or the combination of the other impedances mentioned, including the telephone equipment at the telephone station 1ZA.

The other pairs of line circuits individual to the other pairs of telephone stations in the various areas are respectively arranged in the A loop and in the B loop and are balanced with respect to each other, in the manner explained above.

As previously noted, the simulating impedance network 151 and the operator position 152 are respectively arranged in the A loop and in the B loop and are paired with respect to each other. More particularly, when the repeater 300 in the simulating impedance network 151 and the repeater 700 in the operator position 152 are either unloaded or loaded, the A loop and the B loop are balanced with respect to the amplifier network 171. This is accomplished by balancing the impedance of the primary windings 301 and 302 of the repeater 300 in the simulating impedance network 151 with respect to the impedance of the primary windings 701 and 702 of the repeater 700 in the operator position 152 when the repeaters mentioned are unloaded, and by balancing the impedance connected to the secondary windings 303 and 304 of the repeater 300 in the simulating impedance network 151 with respect to the impedance connected to the secondary windings 703 and 704 of the repeater 700 in the operator position 152 when the repeaters mentioned are loaded. More particularly, in the operator position 152, the effective impedance produced by the line pad 730, the secondary windings 703 and 704 of the repeater 700, the upper and lower windings of the impedance element 1705, the repeater 765 and the receiver 757 and the transmitter 759 at the operator position 152 is fixed at a given value when the repeater 700 is loaded by correctly adjusting the line pad 730. Similarly, in the simulating impedance network 151, the effective impedance produced by the simulating pad 310, the secondary windings 303 and 304 of the repeater 300 and the upper and lower windings of the impedance element 1305 is fixed at a given value when the repeater 300 is loaded by correctly adjusting the simulating pad 310. Accordingly the repeater 700 in the operator position 152 will balance the repeater 300 in the simulating impedance network 151 when the repeaters mentioned are loaded.

Also, in the operator position 152, the impedance of the simulating pad 710 is initially set to equal the effective impedances of the line pad 730, the repeater 765 and the receiver 757 and the transmitter 759 at the operator position 152, whereby the repeater 768 is equally loaded by the simulating pad 710 or the combination of the other impedances mentioned, including the receiver 757 and the transmitter 759 at the operator position 152.

Accordingly the A loop and the B loop are balanced with respect to each other at all times due to the relationship of the simulating im-

pedance network 151 with respect to the operator position 152.

A better understanding of the connection and arrangement of the apparatus incorporated in the telephone system will be facilitated from a consideration of the operation of the various pieces of apparatus incident to the extension of the various calls therein, as will appear hereinafter.

Conference call from the operator position

Considering now the extension of a conference call from the operator position 152 to all or to selected ones of the telephone stations in each of the areas X, Y and Z, the operator first prepares the operator position 152 by removing the receiver 757 from the associated switchhook, whereby the hook switch S760 is operated. When the hook switch S760 is thus operated there is completed, at the contacts 761 thereof, an obvious circuit for energizing the transmitter 759 in series circuit relation with the winding of the answer relay R830, thereby to cause the latter relay to operate. Also when the hook switch S760 is operated there is prepared, at the contacts 762 thereof, a circuit traced hereinafter for energizing the receiver 757. Upon operating, the answer relay R830 interrupts, at the contacts 832, a point in a circuit traced herein after for energizing the winding of the alarm relay R870, and prepares, at the contacts 831, a point in a circuit traced hereinafter for energizing the winding of the cutoff relay R840. Also the answer relay R830 completes, at the contacts 833, a circuit, including the resistor 814 and the contacts 756 of the receiver transfer key K753, for heating the filamentary cathode 747 of the amplifier tube 744. Also it is noted that negative battery potential is applied by way of the resistor 748 to the control electrode 746 of the amplifier tube 744, thereby to establish a negative control bias for the amplifier tube 744 above its cutoff point.

The operator at the operator position 152 then operates the common start key K810, thereby to complete, at the contacts 813 thereof, an obvious circuit for illuminating the common answer pilot lamp L820 in order to indicate to the operator that the telephone circuit is busy. Also, at the contacts 812 of the common start key K810, there is completed a path for applying ground potential to the conductor C826 in order to complete an obvious circuit for energizing the winding of the amplifier start relay R850, thereby to cause the latter relay to operate. Finally, at the contacts 811 of the common start key K810, there is completed an obvious path for applying ground potential to the ring start conductor C777. The application of ground potential to the ring start conductor C777 completes a circuit including the lower winding of the impedance element I305, the winding 304 of the repeater 300, the resistors 312 and 311, the winding 303 of the repeater 300 and the upper winding of the impedance element I305 for loading the repeater 300 in the simulating impedance network 151. Also the application of ground potential to the ring start conductor C777 completes an obvious circuit, including the contacts 802 of the common talk key K800, for energizing the winding of the pad switching relay R770, thereby to cause the latter relay to operate. Upon operating, the pad switching relay R770 completes, at the contacts 773 and 776, a circuit including the upper winding of the impedance element I765, the winding

703 of the repeater 700, the simulating pad 710, the winding 704 of the repeater 700 and the lower winding of the impedance element 1705 for loading the repeater 700. Accordingly, at this time, the repeater 300 in the simulating impedance network 151 and the repeater 700 in the operator position 152 are loaded, thereby to maintain the balanced relation between the A loop and the B loop extending to the amplifier network 171.

Finally the application of ground potential to the ring start conductor C777 completes a plurality of multiple circuits for energizing the upper windings of the pad switching relays in the various line circuits. The circuit for energizing the upper winding of the pad switching relay R460 in the line circuit 126 illustrated extends from the grounded ring start conductor C777 by way of the contacts 562, the hold conductor C581, the contacts 454 and 443 and the upper winding of R460 to battery. When thus energized the pad switching relay R460 operates to interrupt, at the contacts 463 and 468, points in a connection traced hereinafter between the repeater 400 and the line pad 430; to interrupt, at the contacts 461 and 466, points in a connection traced hereinafter between the line pad 430 and the adapter circuit 136; to prepare, at the contacts 462 and 467, a circuit traced hereinafter for projecting ringing current over the adapter circuit 136; and to complete, at the contacts 464, an obvious circuit, including the simulating pad 410 and the secondary windings 403 and 404 of the repeater 400, for energizing the upper and lower windings of the line relay R405 in series circuit relation, whereby the latter relay operates. Accordingly, at this time, the repeater 400 is loaded. Also the pad switching relay R460 interrupts, at the contacts 469, a point in a circuit traced hereinafter for energizing the winding of the hold relay R440; prepares, at the contacts 461', a further point in the previously mentioned circuit for projecting ringing current over the adapter circuit 136; and completes, at the contacts 462', an obvious circuit for energizing the upper winding of the ring relay R530. Also the pad switching relay R460 completes, at the contacts 462', a multiple circuit including the contacts 525, the contacts of individual ring control key K827, the contacts 534 and the resistor 818 for energizing the lower winding of the ring relay R530, in the event the individual ring control key K827 occupies its operated position. Assuming for the present that the individual ring control key K827 occupies its restored position, the above-traced circuit for energizing the lower winding of the ring relay R530 is not completed; accordingly, the latter relay operates. At this point it is noted that the ring relay R530 is of the differential type and is not operated when both the upper and lower windings thereof are energized.

Upon operating, the ring relay R530 completes, at the contacts 532, the previously mentioned circuit for projecting ringing current over the adapter circuit 136. This circuit extends from ground by way of the contacts 462, 541, 551, 571 and 631, the winding 643 of the repeater 640, the condenser 622, the winding 644 of the repeater 640, the contacts 634, 572, 553, 544 and 467, the winding of the ring cutoff relay R510, and the contacts 524, 461' and 532 to the generator conductor C515 having battery potential thereon. Accordingly ringing current traverses the above-traced circuit at this time, causing the windings 70

643 and 644 of the repeater 640 to induce a corresponding ringing voltage in the windings 641 and 642 of the repeater 640, whereby ringing current traverses a circuit extending from one terminal of the winding 641 of the repeater 640 by way of the contacts 633, one of the line conductors of the trunk line 132, the windings 653 and 654 of the repeater 650, the other line conductor of the trunk line 132, the contacts 636 and the winding 642 of the repeater 640 to the other terminal of the winding 641 thereof. The ringing current traversing the windings 653 and 654 of the repeater 650 induces ringing voltage in the windings 651 and 652 thereof; whereby ringing current traverses a circuit extending from one terminal of the winding 651 of the repeater 650 by way of one of the line conductors of the telephone line 122, the ringer at the telephone station 12B bridged between the two line conductors of the telephone line 122, the other line conductor of the telephone line 122, the winding 652 of the repeater 650 and the condenser 657 to the other terminal of the winding 651 of the repeater 650. Accordingly the ringer at the telephone station 12B is operated in order to indicate the presence of a conference call on the telephone system.

In view of the foregoing explanation of the mode of operation of the line circuit 126 in response to the application of ground potential to the ring start conductor C777, whereby the repeater 400 is loaded and ringing current is projected over the telephone line 122 to the telephone station 12B, it will be understood that each of the other line circuits 105, 106 etc. is responsive to the application of ground potential to the ring start conductor C777 in a like manner, whereby the repeater in each line circuit 105, 106 etc. is loaded and ringing current is projected over the associated telephone lines 101, 102 etc. to the telephone stations 1XA, 1XB etc.

As previously noted, when the common start key K810 was operated the amplifier start relay R850 operated. Upon operating, the amplifier start relay R850 completes, at the contacts 851, an obvious path for applying ground potential to the amplifier start conductor C815, thereby to complete an obvious circuit for energizing the winding of the amplifier start slave relay R260, whereby the latter relay operates. Upon operating, the amplifier start slave relay R260 completes, at the contacts 262, an obvious path for applying ground potential to the screen grids 233 and 243 of the respective amplifier tubes 230 and 240 and an operating circuit for the two parallel connected amplifier tubes 230 and 240, whereby the two amplifier tubes 230 and 240 are rendered conductive. The operating circuit for the two amplifier tubes 230 and 240 extends from ground by way of the contacts 262, the monitor jack J290 and the primary winding 201 of the repeater 200 to the plates 231 and 241 of the respective amplifier tubes 230 and 240, and from battery by way of the plate alarm relay R280 and the resistor 253 to the cathodes 232 and 242 of the respective amplifier tubes 230 and 240. When the two amplifier tubes 230 and 240 are thus rendered conductive, space current traverses the two parallel connected amplifier tubes and the winding of the plate alarm relay R280 is energized. The latter relay now operates, in the event the two amplifier tubes 230 and 240 are operating properly. Upon operating, the plate alarm relay R280 interrupts, at the con-

acts 281, a previously prepared circuit for illuminating the alarm lamp L291, a point in the last-mentioned circuit being prepared at the contacts 261 incident to the operation of the amplifier start slave relay R260.

At this point it is noted that, in the event the two amplifier tubes 230 and 240 do not operate, in the manner explained above, incident to the operation of the amplifier start slave relay R260, the above-traced circuit for energizing the winding of the plate alarm relay R280 is not completed and the latter relay remains in its restored position. In this event the above-mentioned circuit for illuminating the alarm lamp L291 is completed and extends from ground by way of the alarm lamp L291, the contacts 281 and 261 and the resistor 272 to battery. Also, in the event either one of the cathode heaters 235 and 245 of the respective amplifier tubes 230 and 240 burns up, the previously traced normally completed circuit for energizing the winding of the filament alarm relay R270 is interrupted, thereby to cause the latter relay to restore. Upon restoring, the filament alarm relay R270 completes, at the contacts 271, an obvious circuit, including the resistor 272, for illuminating the alarm lamp L291. The illumination of the alarm lamp L291 indicates that the amplifier tubes 230 and 240 are not operating properly, whereupon the attendant in the central office replaces the defective amplifier tube in order again to render the amplifier network 171 operative.

Continuing now with the operation of the amplifier network 171 it is noted that the current traversing the parallel connected amplifier tubes 230 and 240 traverses the primary winding 201 of the repeater 200 which is inductively coupled to the secondary winding 202 thereof. As previously pointed out, the secondary winding 202 of the repeater 200 is commonly included in the A loop and in the B loop. However, since the impedances of the A loop and the B loop are balanced the windings 206 and 207 of the repeater 205, respectively included in the loop A and in the loop B, are balanced and no signal voltage appears between the terminals of the transmission equalizer circuit 210. Accordingly the transformer 220 is not controlled at this time in order to govern the potential applied to the control electrodes 234 and 244 of the respective amplifier tubes 230 and 240 by way of the potentiometer 225 connected to the transformer 220. Hence, there is no singing of the amplifier network at this time due to the balance maintained between the impedances of the loop A and the loop B.

Continuing now with the initiation of the conference call from the operator position 152, the operator thereat next operates the common talk key K800. When the common talk key K800 is thus operated there is prepared, at the contacts 801 and 803 thereof, an alternative circuit for loading the repeater 100; and there is interrupted, at the contacts 802 thereof, the previously traced circuit for energizing the winding of the pad switching relay R170, thereby to cause the latter relay to restore. Upon restoring, the pad switching relay R170 completes, at the contacts 771, 772, 774 and 775, an alternative circuit for loading the repeater 100 and an operative connection between the repeater 100 and the repeater 765. Also the pad switching relay R170 interrupts, at the contacts 773 and 776, the previously traced original circuit, including the

simulating pad 710, for loading the repeater 100. At this time the operative connection between the repeater 100 and the repeater 765 extends from ground by way of the upper winding of the impedance element 1705, the winding 703 of the repeater 100, the contacts 772, the resistors 732 and 731, the contacts 771, the contacts 801 of the common talk key K800, the windings 768 and 767 of the repeater 765, the contacts 803 of the common talk key K800, the contacts 774, the resistors 733 and 734, the contacts 775, the winding 704 of the repeater 100 and the lower winding of the impedance element 1705 to battery. Accordingly, at this time, the repeater 100 in the operator position 152 is alternatively loaded by the repeater 765 and the receiver 757 and the transmitter 759 an amount equal to the original loading thereof by the simulating pad 710. Hence, the balance of the loop A and the loop B is maintained.

Continuing now with the extension of the conference call from the operator position 152, the call is answered at the telephone station 12B when the person thereat removes the receiver of the telephone instrument from its associated switchhook, thereby to complete an operating circuit for energizing the winding of the simplex relay R620 in the line circuit 126. The above-mentioned circuit extends from ground by way of the winding 651 of the repeater 650, one of the line conductors of the telephone line 122, the telephone instrument at the telephone station 12B, the other line conductor of the telephone 122, the winding 652 of the repeater 650, the impedance element 656, the windings 653 and 654 of the repeater 650, the line conductors of the trunk line 132, the contacts 633 and 636, the windings 641 and 642 of the repeater 640 and the winding of the simplex relay R620 to battery. It is noted that this operating circuit comprises a simplex circuit including the line conductors of the trunk line 132 connected in parallel relation. When this operating circuit is thus completed the simplex relay R620 operates to complete, at the contacts 621, an obvious path for short-circuiting the condenser 622 and a metallic circuit substantially identical to that previously traced for energizing the winding of the ring cutoff relay R510. Shortly after the winding of the ring cutoff relay R510 is thus energized the latter relay operates, the ring cutoff relay R510 being of the combination slow-to-operate and slow-to-release type. Upon operating, the ring cutoff relay R510 completes, at the contacts 511, an obvious circuit, including the contacts 451, for energizing the winding of the answer relay R450. When thus energized the answer relay R450 operates to complete, at the contacts 453, an obvious holding circuit, including the grounded hold conductor C581, for energizing the winding thereof. Also the answer relay R450 interrupts, at the contacts 451, the previously traced operating circuit for energizing the winding thereof; and interrupts, at the contacts 454, the previously traced circuit for energizing the winding of the pad switching relay R460, thereby to cause the latter relay to restore. Further the answer relay R450 interrupts, at the contacts 457, a point in a circuit traced hereinafter for energizing the winding of the supervisory relay R610; and prepares, at the contacts 456, a circuit traced hereinafter for illuminating the individual answer lamp L817.

Upon restoring, the pad switching relay R460 interrupts, at the contacts 464, the previously

traced circuit, including the simulating pad 410, for loading the repeater 400; and completes, at the contacts 461, 463, 466 and 468, an alternative circuit for loading the repeater 400 and an operative connection between the repeater 400 and the repeater 640. The operative connection between the repeater 400 and the repeater 640 extends from ground by way of the upper winding of the line relay R450, the winding 403 of the repeater 400, the contacts 463, the resistors 432 and 431, the contacts 461, 541, 551, 571 and 631, the winding 643 of the repeater 640, the contacts 621, the winding 644 of the repeater 640, the contacts 634, 572, 553, 544 and 466, the resistors 433 and 434, the contacts 468, the winding 404 of the repeater 400 and the lower winding of R405 to battery. When this operative connection between the repeater 400 and the repeater 640 is completed the line relay R405 is retained in its operated position. Also the repeater 640 is operatively connected to the repeater 650 and the repeater 650 is operatively connected to the telephone station 1ZB; the two last-mentioned connections being identical to those previously traced for projecting ringing current from the line circuit 126 over the trunk line 132 and the telephone line 122 to the telephone station 1ZB. Hence the telephone station 1ZB is operatively connected by way of the adapter circuit 136 to the repeater 400, which connection includes the line pad 430. Thus, at this time, the repeater 400 is loaded an amount equal to the prior loading thereof by way of the simulating pad 410. Accordingly the impedance of the loop B is not changed when the call is answered at the telephone station 1ZB; and the A loop and the B loop are still balanced with respect to each other.

Also, upon restoring, the pad switching relay R460 interrupts, at the contacts 462, 467 and 461', points in the previously traced circuit for projecting ringing current over the adapter circuit 136 to the telephone station 1ZB, whereby the previously traced circuit for energizing the winding of the ring cutoff relay R510 is interrupted in order to cause the latter relay to restore shortly thereafter, the ring cutoff relay R510 being of the combination slow-to-operate and slow-to-release type, as previously noted. Also the pad switching relay R460 completes, at the contacts 469, a circuit, including the contacts 521 and 406, for energizing the winding of the hold relay R440, thereby to cause the latter relay to operate. Also the pad switching relay R460 interrupts, at the contacts 462', the previously traced circuit for energizing the upper winding of the ring relay R530, thereby to cause the latter relay to restore. Previously, when the ring relay R530 operated it completed, at the contacts 533, an obvious circuit for illuminating the individual ring lamp L931, thereby to indicate to the operator at the operator position 152 that ringing current was being projected over the telephone line 122 to the telephone station 1ZB. Accordingly, upon restoring, the ring relay R530 interrupts, at the contacts 533, the above-mentioned circuit for illuminating the individual ring lamp L931 thereby to indicate to the operator at the operator position 152 that the projection of ringing current over the telephone line 122 to the telephone station 1ZB has been interrupted. Further the ring relay R530 interrupts, at the contacts 532, a further point in the previously traced circuit for projecting ringing current over the adapter circuit 136.

Upon operating, the hold relay R440 completes, at the contacts 442, an obvious multiple path for

applying ground potential to the hold conductor C581, thereby positively to insure the retention of ground potential upon the ring start conductor C771. Further the hold relay R440 prepares, at the contacts 441, a point in a circuit traced hereinafter for energizing the winding of the release relay R520 and interrupts, at the contacts 443, a further point in the previously traced circuit for energizing the winding of the pad switching relay R460. Further the hold relay R440 completes, at the contacts 444, an alternative path for applying ground potential to the conductor C826, thereby to insure that the amplifier start relay R850 is retained in its operated position. Finally, the hold relay R440 completes, at the contacts 445, the previously mentioned circuit, including the contacts 456, for illuminating the individual answer lamp L817, thereby to indicate to the operator at the operator position 152 that the conference call has been answered at the telephone station 1ZB.

After the conference call initiated at the operator position 152 has been answered at one of the telephone stations in order to cause operation of the hold relay in the associated line circuit, in the manner explained above, the common start key K810 may be returned to its normal position. When the common start key K810 is thus returned to its normal position there is interrupted, at the contacts 811 thereof, the previously traced original path for applying ground potential to the ring start conductor C771. However, ground potential is retained upon the last-mentioned conductor due to the operated position of the hold relay in the line circuit individual to the telephone station at which the conference call has been answered, as previously noted. Similarly, at the contacts 812 of the common start key K810, there is interrupted the previously traced original path for applying ground potential to the conductor C826. However, ground potential is retained upon the last-mentioned conductor due to the operated position of the hold relay in the line circuit individual to the telephone station at which the conference call has been answered, as previously noted. Finally, at the contacts 813 of the common start key K810, the previously traced circuit for illuminating the common answer pilot lamp L820 is interrupted.

In view of the foregoing explanation of the mode of operation of the line circuit 126 to interrupt the projection of ringing current over the telephone line 122 extending to the telephone station 1ZB and to complete an operative connection between the telephone station 1ZB and the repeater 400, in response to the answering of the call at the telephone station 1ZB, it will be understood that the other line circuits are operative in a similar manner in order to accomplish similar functions in response to the answering of the call at the corresponding telephone stations.

Accordingly, at this time, an operative connection is completed between the operator position 152 and at least the telephone station 1ZB in the B loop. Subsequently, as the call is answered at other stations in the B loop, the connection includes the stations mentioned. Also, as the call is answered at other stations in the A loop, an operative connection is completed between the operator position 152 and the other stations mentioned. Finally it is pointed out that each station which has answered the conference call is operatively connected both to the operator position 152 and to each other station which has

answered the conference call, regardless of the loop, including the answering telephone station.

Now assume that the conference call initiated at the operator position 152 has been answered at the telephone stations 1XA, 1YA, 1ZA etc. in the A loop and at the telephone stations 1XB, 1YB, 1ZB etc. in the B loop. When the operator at the operator position 152 speaks the transmitter 759 is operated, whereby a signal current is generated which traverses a circuit extending from ground by way of the winding 766 of the repeater 765, the condenser 764, the transmitter 759 and the contacts 761 of the hook switch S160 to ground. The signal current traversing the winding 766 of the repeater 765 induces a corresponding signal voltage in the windings 761 and 768 of the repeater 765, whereby a corresponding signal current traverses the previously traced circuit including the windings 703 and 704 of the repeater 700 and the condenser 709. The signal current traversing the windings 703 and 704 of the repeater 700 induces a corresponding signal voltage in the windings 701 and 702 of the repeater 700, whereby a corresponding signal current traverses the previously traced circuit including the B loop. The signal current traversing the B loop, including the windings 207 and 209 of the repeater 205, causes a difference of potential to exist between the mid taps between the windings 206, 208 and 207, 209 of the repeater 205, whereby a corresponding signal voltage is impressed between the terminals of the transmission equalizer circuit 210 and, consequently, across the terminals of the primary winding 221 of the transformer 220. Thus, a corresponding signal current traverses the primary winding 221 of the transformer 220 and induces a corresponding signal voltage in the secondary winding 222 thereof, whereby a corresponding signal current traverses the previously traced circuit including the secondary winding 222 of the transformer 220 and the potentiometer 225. The signal current traversing the potentiometer 225 produces a signal voltage change which is applied by way of the resistors 251 and 252 to the control electrodes 234 and 244 of the respective amplifier tubes 230 and 240, whereby the conductivity of the amplifier tubes 230 and 240 is changed. Accordingly the amplifier tubes 230 and 240 amplify the signal voltage applied to the respective control electrodes 234 and 244 thereof, whereby the amplified signal voltage is productive of an amplified signal current traversing the previously traced circuit including the primary winding 201 of the repeater 200. The amplified signal current traversing the primary winding 201 of the repeater 200 induces a corresponding amplified signal voltage in the secondary winding 202 of the repeater 200, which amplified signal voltage causes a corresponding amplified signal current to traverse the A and B loops. The amplified signal currents traversing the A and B loops respectively include the pairs of windings 206, 208 and 207, 209 of the repeater 205, whereby the signal potential produced at the mid taps between the pairs of windings 206, 208 and 207, 209 of the repeater 205 is canceled out. Accordingly the amplified signal current traversing the A loop and the B loop is canceled out in the repeater 205, thereby preventing subsequent regeneration and the consequent singing of the amplifier network 171.

The amplified signal current traversing the A loop includes the repeaters in the line circuits 105, 125 etc. and the booster transformer 141, whereby a corresponding amplified signal current

is projected over the telephone lines 101, 121 etc. to the telephone stations 1XA, 1ZA etc. The amplified signal current traversing the booster transformer 141 causes the last-mentioned transformer to induce a corresponding amplified signal voltage in the repeaters in the line circuits 115 etc., whereby an amplified signal current is projected over the telephone lines 111 etc. to the telephone stations 1YA etc. Similarly, the amplified signal current traversing the B loop includes the repeaters in the line circuits 106, 126 etc. and the booster transformer 142, whereby a corresponding amplified signal current is projected over the telephone lines 102, 122 etc. to the telephone stations 1XB, 1ZB etc. The amplified signal current traversing the booster transformer 142 causes the last-mentioned transformer to induce a corresponding amplified signal voltage in the repeaters in the line circuits 116 etc., whereby an amplified signal current is projected over the telephone lines 112 etc. to the telephone stations 1YB etc.

Also the amplified signal current traversing the B loop includes the windings 701 and 702 of the repeater 700, whereby a corresponding amplified signal voltage is induced in the windings 703 and 704 of the repeater 700 in order to cause a corresponding amplified signal current to traverse the previously traced circuit, including the windings 767 and 768 of the repeater 765. A portion of the amplified signal current traversing the winding 767 of the repeater 765 by-passes the winding 768 thereof by way of a circuit including the condenser 763, the contacts 751 of the receiver transfer key K750, the winding 736 of the transformer 735 and the contacts 754 of the receiver transfer key K750, assuming that the receiver transfer key K750 occupies its restored position at this time. The amplified signal current traversing the winding 736 of the transformer 735 induces a corresponding amplified signal voltage in the winding 737 thereof, whereby a corresponding amplified signal current traverses the previously traced circuit including the resistor 748. The amplified signal current traversing the winding 737 of the transformer 735 and the resistor 748 varies the bias applied to the control electrode 746 of the amplifier tube 744, whereby the conductivity of the last-mentioned tube is changed in order to amplify further the signal current. The further amplified signal current traverses an obvious circuit including the winding 741 of the repeater 740 and the electron stream of the amplifier tube 744, whereby a corresponding further amplified signal voltage is induced in the winding 742 of the repeater 740 in order to cause a corresponding further amplified signal current to traverse an obvious circuit including the potentiometer 743. The receiver 757 at the operator position 152 is operatively connected by way of the contacts 753 of the receiver transfer key K750 and the contacts 762 of the hook switch S160 to the potentiometer 743, whereby the further amplified signal current traverses the receiver 757 in order to cause operation thereof.

More particularly, the amplified signal current traversing the B loop includes the windings 401 and 402 of the repeater 400, whereby a corresponding amplified signal voltage is induced in the windings 403 and 404 of the repeater 400 in order to cause a corresponding amplified signal current to traverse the previously traced connection between the repeater 400 and the repeater 640. The amplified signal current traversing the windings 643 and 644 of the repeater 640 induces

a corresponding amplified signal voltage in the windings 641 and 642 thereof, whereby a corresponding amplified signal current traverses the previously traced connection, including the trunk line 132, extending between the repeater 640 and the repeater 650. The amplified signal current traversing the windings 653 and 654 of the repeater 650 induces a corresponding amplified signal voltage in the windings 651 and 652 thereof, whereby a corresponding amplified signal current traverses the previously traced connection, including the telephone line 122, extending to the telephone station 1ZB in order to cause operation of the receiver at the last-mentioned telephone station.

When the person at any one of the telephone stations speaks a signal current is generated by the transmitter thereat in order to cause operation of the repeater in the associated line circuit. This operation of the repeater in the associated line circuit causes unbalance between the A loop and the B loop, regardless of which loop includes the repeater, whereby the amplifier network 171 is controlled in order to return a corresponding amplified signal current over the A and B loops, all in the manner previously explained.

At any time the operator at the operator positions 152 may operate the receiver transfer key K750, thereby to cut out the local amplifier network and to connect the receiver 757 directly to the repeater 765. When the receiver transfer key K750 is thus operated there is interrupted, at the contacts 753 thereof, the previously traced operative connection between the receiver 757 and the potentiometer 743. Also, at the contacts 756 of the receiver transfer key K750, there is interrupted the previously traced circuit for heating the filamentary cathode 741 of the amplifier tube 744. Further, at the contacts 751 and 754 of the receiver transfer key K750, the previously traced connection between the winding 736 of the transformer 135 and the repeater 765 is interrupted. Finally, at the contacts 752 and 755 of the receiver transfer key K750, an operative connection is completed between the receiver 757 and the repeater 765. The last-mentioned circuit extends from the lower terminal of the winding 768 of the repeater 765 by way of the contacts 755 of the receiver transfer key K750, the receiver 757, the contacts 762 of the hook switch S160, the contacts 752 of the receiver transfer key K750 and the condenser 763 to the junction between the lower terminal of the winding 767 and the upper terminal of the winding 768 of the repeater 765.

Furthermore, the operator at the operator position 152 may at any time disable the transmitter 759 so that she may speak without being heard over the telephone system merely by operating the transmitter shunt key K758. When the transmitter shunt key K758 is thus operated an obvious path is completed for short-circuiting the transmitter 759 and an obvious alternative holding circuit for energizing the winding of the answer relay R830 is completed.

In the foregoing explanation of the mode of operation of the line circuit 126 incident to the initiation of a conference call from the operator position 152, it was assumed that the individual ring control key K827 occupied its restored position, whereby the line circuit 126 was controlled in order to cause ringing current to be projected over the telephone line 122 extending to the telephone station 1ZB. However, it may be desirable for the operator at the operator position 152 to initiate a conference call in the manner pre-

viously explained, excluding one or more telephone stations, whereby the associated line of circuits are controlled in order to prevent the projection of ringing current over the associated telephone lines to the telephone stations mentioned. Now assume that the telephone station 1ZB is not to be signaled in conjunction with the initiation of the present conference call from the operator position 152. In this event the operator at the operator position 152 first operates the individual ring control key K827 corresponding to the line circuit 126 and consequently to the telephone station 1ZB. When the individual ring control key K827 is thus operated there is prepared, at the contacts thereof, a circuit traced hereinafter for energizing the lower winding of the ring relay R530.

The operator at the operator position 152 then proceeds to initiate the extension of the conference call in the manner previously explained, whereby the pad switching relays in the various line circuits are obtained, all in the manner previously described. In the present example, when the pad switching relay R460 operates in the line circuit 126 it completes, at the contacts 462', a multiple circuit for energizing the upper and lower windings of the ring relay R530. This circuit extends from ground by way of the contacts 462' and 525 and the upper winding of R530 to battery and from ground by way of the contacts 462' and 525, the lower winding of R530, the contacts of the individual ring control key K827, the contacts 534 and the resistor 818 to battery. Accordingly, in the present example, both the upper and the lower windings of the ring relay R530 in the line circuit 126 are energized, whereby the last-mentioned relay remains in its restored position in view of the fact that the ring relay R530 is of the differential type, as previously noted. Accordingly the previously traced circuit for projecting ringing current over the telephone line 122 to the telephone station 1ZB is not completed and the telephone station 1ZB is not signaled in conjunction with the present conference call.

In view of the foregoing explanation of the arrangement for precluding the telephone station 1ZB from being signaled incident to the initiation of a conference call at the operator position 152, it will be readily understood that the signaling of any number of stations may be precluded by merely operating the respective individual ring control keys. In the event the telephone station 1ZB is normally not signaled in conjunction with the initiation of conference calls, but the operator wishes to signal the last-mentioned station in conjunction with the present conference call, she may do so in a ready manner by operating the individual ring start key K920, even though the individual ring control key K827 occupies its operated position. In the present example, when the individual ring start key K920 is thus operated there is completed an obvious circuit for illuminating the individual ring lamp L931, and a multiple path, including the contacts 534, the individual ring control key K827 and the contacts 525 and 462', for short-circuiting the lower winding of the ring relay R530. When the lower winding of the ring relay R530 is thus short-circuited, while the upper winding thereof is energized in the manner previously explained, the latter relay operates. Upon operating, the ring relay R530 completes, at the contacts 533, an alternative path for short-circuiting the lower winding thereof, this circuit including the indi-

vidual ring control key K827 and the contacts 525 and 462'. Also, upon operating, the ring relay R530 completes, at the contacts 532, the previously traced circuit for projecting ringing current over the telephone line 122 to the telephone station 1ZB, whereby the ringer at the last-mentioned station is operated in the manner previously explained. The subsequent operation of the line circuit 126, in response to the answering of the call at the telephone station 1ZB, is the same as that previously described.

In the event the operator at the operator position 152 wishes to insure that each telephone station in a first group is signaled, regardless of the position of the respective individual ring control keys in conjunction with the present conference call, this may be accomplished by operating the first group ring start key K941, thereby to complete an obvious circuit for energizing the winding of the first group ring start relay R950, whereupon the latter relay operates. Upon operating, the first group start relay R950 completes, at the contacts 951 etc., obvious paths for applying ground potential to the various conductors C952 etc. extending to the corresponding line circuits 126 etc., whereby each of the line circuits mentioned in the first group is controlled in order to cause ringing current to be projected over the associated telephone line to the corresponding telephone station, in the manner previously explained. Similarly, in the event the operator at the operator position 152 wishes to insure that each telephone station in a second group or a third group is signaled, regardless of the position of the respective individual ring control keys in conjunction with the present conference call, this may be accomplished by selectively operating the second and third group ring start keys K942 and K943 in order to control the operation of the second and third group ring start relays R960 and R970, in an obvious manner. Finally, in the event the operator at the operator position 152 wishes to insure that each telephone station in each group is signaled, regardless of the position of the respective individual ring control keys in conjunction with the present conference call, this may be accomplished merely by operating the all-groups ring start key K944, thereby to control each of the ring start relays R950, R960 and R970 in an obvious manner.

Now assuming that the present conference call is in progress, when the person at the telephone station 1ZB replaces the receiver of the telephone instrument thereat upon its associated switchhook the previously traced circuit for energizing the winding of the simplex relay R620 is interrupted, thereby to cause the latter relay to restore. Upon restoring, the simplex relay R620 interrupts, at the contacts 621, the previously traced connection extending between the repeater 440 and the repeater 400, whereby the previously traced circuit for energizing the upper and lower windings of the line relay R405 is interrupted in order to cause the latter relay to restore. Upon restoring, the line relay R405 interrupts, at the contacts 406, the previously traced circuit for energizing the winding of the hold relay R440; however, the latter relay does not immediately restore as it is of the slow-to-release type. Also the line relay R405 completes, at the contacts 407, a circuit, including the contacts 521, 469 and 441 and the resistor 513, for energizing the winding of the release relay R520. When the release relay R520 is thus energized it operates to complete, at the contacts 522, an obvious holding circuit, in-

cluding the grounded hold conductor C581, for energizing the winding thereof; and to interrupt, at the contacts 521, the previously traced original circuit for energizing the winding thereof. Also the release relay R520 prepares, at the contacts 523, an alternative circuit traced hereinafter for energizing the winding of the ring cutoff relay R510; interrupts, at the contacts 524, a further point in the previously traced circuit for projecting ringing current over the telephone line 122 extending to the telephone station 1ZB; and interrupts, at the contacts 525, a further point in the previously traced circuit for energizing the upper winding of the ring relay R530. Finally the release relay R520 completes, at the contacts 526, an obvious circuit for energizing the lower winding of the pad switching relay R460, thereby to cause the latter relay to reoperate. Upon reoperating, the pad switching relay R460 completes, at the contacts 464, the previously traced circuit, including the simulating pad 440, for energizing the upper and lower windings of the line relay R405, thereby to cause the latter relay to reoperate.

Shortly after the release relay R520 operates the hold relay R440 restores, as previously noted. Upon restoring, the hold relay R440 interrupts, at the contacts 444, a multiple point in the previously traced circuit for energizing the winding of the amplifier start relay R850; and interrupts, at the contacts 445, the previously traced circuit for illuminating the individual answer lamp L817, thereby to indicate to the operator at the operator position 152 that the person at the telephone station 1ZB has replaced the receiver of the telephone instrument thereat upon its associated switchhook at this time. At this time, the conference connection is maintained between the operator position 152 and the other telephone stations which are still connected to the associated telephone lines. In view of the fact that the simulating pad 440 in the line circuit 126 maintains the repeater 400 therein loaded, the B loop is maintained in a balanced-condition with respect to the A loop, in the manner previously explained.

At any time prior to the ultimate release of the conference connection the person at the telephone station 1ZB may again remove the receiver of the telephone instrument thereat from its associated switchhook and reenter the conference connection. More particularly, when the receiver of the telephone instrument at the telephone station 1ZB is again removed from its associated switchhook the previously traced circuit for energizing the winding of the simplex relay R620 is recompleted, thereby to cause the latter relay to reoperate. Upon reoperating, the simplex relay R620 completes, at the contacts 621, the previously mentioned alternative circuit for energizing the winding of the ring cutoff relay R510. This circuit extends from ground by way of the contacts 462, 541, 551, 571 and 631, the winding 643 of the repeater 440, the contacts 621, the winding 644 of the repeater 440, the contacts 634, 512, 553, 544 and 467, the winding R510, the contacts 523 and the resistor 514 to battery. Shortly after the winding of the ring cutoff relay R510 is thus energized the latter relay reoperates. Upon reoperating, the ring cutoff relay R510 completes, at the contacts 541, a path, including the contacts 452 and 522 and the grounded hold conductor C581, for short-circuiting the winding of the release relay R520, whereby the latter relay restores. Upon restoring, the release relay R520 interrupts, at the contacts 521, the previously traced circuit for energizing the winding of the line relay R405; and the contacts 523, the previously traced circuit for energizing the winding of the simplex relay R620; and the contacts 524, the previously traced circuit for energizing the winding of the ring cutoff relay R510. Finally the release relay R520 completes, at the contacts 525, the previously traced circuit for energizing the upper winding of the ring relay R530.

contacts 522, the previously traced path for short-circuiting the winding thereof, and interrupts, at the contacts 523, the above-traced alternative circuit for energizing the winding of the ring cut-off relay R510. Further the release relay R520 interrupts, at the contacts 526, the previously traced circuit for energizing the lower winding of the pad switching relay R460, thereby to cause the latter relay to restore. Upon restoring, the pad switching relay R460 recompletes, at the contacts 461, 463, 466 and 468, the previously traced connection between the repeater 400 and the repeater 640, whereby the previously traced circuit for energizing the upper and lower windings of the line relay R405 is recompleted, thereby to retain the latter relay in its operated position. Also, upon restoring, the pad switching relay R460 recompletes, at the contacts 469, the previously traced circuit for energizing the winding of the hold relay R440, thereby to cause the latter relay to reoperate. Upon reoperating, the hold relay R440 recompletes, at the contacts 444, the previously mentioned multiple path for energizing the winding of the amplifier start relay R850, and recompletes, at the contacts 445, the previously traced circuit for illuminating the individual answer lamp L817, thereby to indicate to the operator at the operator position 152 that the person at the telephone station 1ZB has again removed the receiver of the telephone instrument thereat from its associated switchhook, whereby the telephone station 1ZB is again included in the conference connection.

At the conclusion of the conference connection the person at each telephone station replaces the receiver of the telephone instrument thereat upon its associated switchhook, whereupon the conference connection is released. Now assuming that the person at the telephone station 1ZB was the last to replace the receiver of the telephone instrument thereat upon its associated switchhook, when this is done the previously traced circuit for energizing the winding of the simplex relay R620 is interrupted, thereby to cause the latter relay to restore. Upon restoring, the simplex relay R620 effects the restoration of the line relay R405, the operation of the release relay R520 and the pad switching relay R460 and the reoperation of the line relay R405, all in the manner previously explained. Shortly thereafter the hold relay R440 restores as previously noted. Upon restoring, the hold relay R440 interrupts, at the contacts 442, the last multiple path for applying ground potential to the conductors C581 and C771. When ground potential is removed from the hold conductor C581 the previously traced holding circuits for energizing the windings of the answer relay R450 and the release relay R520 are interrupted, thereby to cause the latter relays to restore. Upon restoring, the release relay R520 effects the restoration of the pad switching relay R460, in the manner previously explained. Also, upon restoring, the hold relay R440 interrupts, at the contacts 444, the last multiple path for applying ground potential to the conductor C826, whereby the amplifier start relay R850 restores. When ground potential is removed from the ring start conductor C771 the other line circuits are released in a manner identical to the release of the line circuit 126 explained above.

Upon restoring, the amplifier start relay R850 interrupts, at the contacts 851, the previously traced circuit for energizing the winding of the

amplifier start slave relay R260, thereby to cause the latter relay to restore. Upon restoring, the amplifier start slave relay R260 interrupts, at the contacts 262, the previously traced operating circuits for the parallel connected amplifier tubes 230 and 240, whereby the plate alarm relay R280 restores. At this time the amplifier network 171 is completely released. The operator at the operator position 152 then restores the common talk key K800, thereby to interrupt, at the contacts 801 and 803 thereof, the previously traced connection extending between the repeater 700 and the repeater 765, whereby the repeater 700 is unloaded. Also, when ground potential is removed from the ring start conductor C771 the previously traced circuit for loading the repeater 300 in the simulating impedance network 151 is interrupted, whereby the last-mentioned repeater is unloaded. Accordingly, at this time, the repeater 700 in the operator position 152, the repeater 300 in the simulating impedance network 151 and the repeater in each of the line circuits 105, 106 etc. is unloaded. Hence, the A loop and the B loop are balanced at this time, as previously noted.

Finally the operator at the operator position 152 may return the receiver 757 to its associated switchhook, thereby to operate the hook switch S760. When the hook switch S760 is thus operated there is interrupted, at the contacts 761, the previously traced circuit for energizing the winding of the answer relay R830, thereby to cause the latter relay to restore. Upon restoring, the answer relay R830 interrupts, at the contacts 833, the previously traced circuit for heating the filamentary cathode 147 of the amplifier tube 744. At this time the apparatus at the operator position 152 is completely released, as well as the apparatus in each of the line circuits 105, 106, etc.

40 Conference call from a telephone station

Considering now the extension of a conference call from a telephone station to the operator position 152 and to all or selected ones of the other telephone stations in each of the areas X, Y and Z, it is assumed that the call is initiated at the telephone station 1ZB in area Z. The call is initiated at the telephone station 1ZB in area Z when the person thereat removes the receiver of the telephone instrument at the telephone station 1ZB from its associated switchhook, whereupon the previously traced simplex circuit for energizing the winding of the simplex relay R620 is completed in order to cause the latter relay to operate. Upon operating, the simplex relay R620 completes, at the contacts 621, the previously traced connection extending between the repeater 640 and the repeater 400, whereupon the upper and lower windings of the line relay R405 are energized causing the last-mentioned relay to operate in the manner previously explained. Upon operating, the line relay R405 completes, at the contacts 406, the previously traced circuit for energizing the winding of the hold relay R440, thereby to cause the latter relay to operate. Upon operating, the hold relay R440 completes, at the contacts 442, the previously mentioned path for applying ground potential to the hold conductor C581 and to the ring start conductor C771. Also the hold relay R440 interrupts, at the contacts 443, a point in the previously traced circuit for energizing the upper winding of the pad switching relay R460, thereby positively to prevent operation of the latter relay.

75 The application of ground potential to the ring start conductor C771 completes the previously

traced circuit, including the contacts 802 of the common talk key K800, for energizing the winding of the pad switching relay R710, thereby to cause the latter relay to operate. Upon operating, the pad switching relay R710 completes, at the contacts 713 and 716, the previously traced circuit, including the simulating pad 710, for loading the repeater 700 at the operator position 152. Also the application of ground potential to the ring start conductor C177 completes the previously traced circuit for loading the repeater 300 in the simulating impedance network 151. Finally, the application of ground potential to the ring start conductor C177 completes multiple circuits for energizing the upper windings of the pad switching relays in each of the line circuits 105, 106 etc. other than in the line circuit 126; whereby the pad switching relay in each of the other line circuits is operated at this time. Accordingly, at this time, the repeater 400 in the line circuit 126 is loaded due to the completion of the previously traced connection between the repeater 640 and the repeater 400, while the repeater in each of the other line circuits 105, 106 etc. is loaded, by the simulating pad therein due to the operation of the pad switching relay therein, as previously noted. Hence, the A loop and the B loop are balanced at this time, as previously explained.

Continuing now with the operation of the line circuit 126, the hold relay R440 also completes, at the contacts 444, the previously traced path for applying ground potential to the conductor C826 and consequently the previously traced circuit for energizing the winding of the amplifier start relay R850, thereby to cause the latter relay to operate. Upon operating, the amplifier start relay R850 completes, at the contacts 851, the previously traced circuit for energizing the winding of the amplifier start slave relay R260 in the amplifier network 171, whereupon the latter relay operates in order to render the multiple connected amplifier tubes 230 and 240 therein conductive at this time. Hence, at this time, the amplifier network 171 supplies current to the A loop and to the B loop in the manner previously explained. Further the hold relay R440 completes, at the contacts 445, a circuit including the contacts 457, for energizing the winding of the supervisory relay R610, thereby to cause the latter relay to operate. Upon operating, the supervisory relay R610 completes, at the contacts 612, an obvious holding circuit, including the grounded hold conductor C581, for energizing the winding thereof. Also the supervisory relay R610 completes, at the contacts 611, an obvious series circuit for illuminating the individual call lamp L932 and for energizing the winding of the call relay R880. The illumination of the individual call lamp L932 indicates to the operator at the operator position 152 that the present conference call was initiated at the telephone station 12B. When thus energized, the call relay R880 operates to complete, at the contacts 881, an obvious circuit for illuminating the common answer pilot lamp L820, thereby to indicate to the operator at the operator position 152 that a conference call is waiting to be answered. Also the call relay R880 completes, at the contacts 882, a circuit, including the contacts 832 and 842, for energizing the winding of the alarm relay R870, thereby to cause the latter relay to operate. Upon operating, the alarm relay R870 completes, at the contacts 871 and 872, an obvious operating circuit for the alarm signal A873, thereby to give

the operator at the operator position 152 an audible alarm indicating that a conference call is waiting to be answered.

Further it is pointed out that the operation of the pad switching relay in each of the line circuits, other than the line circuit 126, causes operation of the ring relay in the line circuit unless the respective individual ring control key occupies its operated position, in the manner previously explained. The operation of the ring relay in each of the line circuits mentioned causes ringing current to be projected over the associated telephone line to the individual telephone station, whereby each of the stations mentioned is signaled in connection with the present conference call. The present conference call is answered at each of the telephone stations which is signaled, when the person thereat removes the receiver of the telephone instrument at the signaled station from its associated switchhook, all in the manner previously explained. When the call is answered at each signaled telephone station the associated line circuit is controlled over the telephone line individual thereto, whereby the pad switching relay in the line circuit is restored in order to interrupt the projection of ringing current to the telephone station mentioned and to complete an operative connection between the telephone station mentioned and the repeater in the associated line circuit, all in the manner previously explained.

The operator at the operator position 152 answers the present conference call by first removing the receiver 157 of the telephone instrument from its associated switchhook, whereby the hook switch S160 is operated. When the hook switch S160 is thus operated there is completed, at the contacts 161, the previously traced operating circuit for the transmitter 159 and for energizing the winding of the answer relay R830 in order to cause the latter relay to operate. Also, at the contacts 162 of the hook switch S160, the previously traced operative connection between the receiver 157 and the potentiometer 143 is completed. Upon operating, the answer relay R830 interrupts, at the contacts 832, the previously traced circuit for energizing the winding of the alarm relay R870, thereby to cause the latter relay to restore. Also the answer relay R830 completes, at the contacts 831, an obvious circuit, including the contacts 882, for energizing the winding of the cutoff relay R840, thereby to cause the latter relay to operate. Further the answer relay R830 completes, at the contacts 833, the previously traced circuit for heating the filamentary cathode 741 of the amplifier tube 144. Upon restoring, the alarm relay R870 interrupts, at the contacts 811 and 812, the previously traced operating circuit for the alarm signal A873. Upon operating, the cutoff relay R840 completes, at the contacts 841, an obvious holding circuit for energizing the winding thereof, and interrupts, at the contacts 842, a further point in the previously traced circuit for energizing the winding of the alarm relay R870.

The operator at the operator position 152 then operates the common talk key K800, thereby to interrupt, at the contacts 802 thereof, the previously traced circuit for energizing the winding of the pad switching relay R710 in order to cause the latter relay to restore. Upon restoring, the pad switching relay R710 interrupts, at the contacts 713 and 716, the previously traced circuit, including the simulating pad 710, for loading the repeater 700, and completes, at the contacts 711,

712, 714 and 715, the previously traced operative connection between the repeater 700 and the repeater 765.

Accordingly, at this time, the repeater 700 in the operator position 152 is loaded by the repeater 765; the position equipment at the operator position 152 is operatively connected to the B loop; the A and B loops are operatively connected to the amplifier network 171; and certain of the telephone stations are operatively connected respectively to the A and B loops. Hence, at this time, the operator and the persons at the various telephone stations in both the A and B loops may converse over the conference connection. As previously pointed out, as the present conference call is sequentially answered at the various telephone stations, these telephone stations are operatively connected to the corresponding one of the loops for communication purposes.

The subsequent release of any telephone station from the conference connection, as well as the ultimate release of the conference connection, under the control of the last telephone station at which the receiver thereat is replaced upon its associated switchhook, is the same as previously explained. When the receivers at all of the telephone stations included in the present conference call are returned to their associated switchhooks, all of the hold relays in the various line circuits 105, 106 etc. are restored; whereupon ground potential is removed from the hold conductor C581 and the ring start conductor C771, all in the manner previously explained. When ground potential is removed from the conductor C581 and the ring start conductor C771 each of the line circuits 105, 106 etc. is released, as previously noted.

More particularly, in the line circuit 126, when ground potential is removed from the hold conductor C581 the previously traced holding circuit for energizing the winding of the supervisory relay R610 is interrupted, thereby to cause the latter relay to restore. Upon restoring, the supervisory relay R610 interrupts, at the contacts 611, the previously traced series circuit for illuminating the individual call lamp L932 and for energizing the winding of the call relay R880, thereby to cause the latter relay to restore. Upon restoring, the call relay R880 interrupts, at the contacts 881, the previously mentioned circuit for illuminating the common answer pilot lamp L820, and interrupts, at the contacts 882, the previously traced holding circuit for energizing the winding of the cutoff relay R840, thereby to cause the latter relay to restore. Furthermore, when each of the line circuits 105, 106 etc. is released, ground potential is removed from the conductor C826, thereby to interrupt the previously mentioned circuit for energizing the winding of the amplifier start relay R850 in order to cause the latter relay to restore. Upon restoring, the amplifier start relay R850 interrupts, at the contacts 851, the previously traced circuit for energizing the winding of the amplifier start slave relay R260 in the amplifier network 171, thereby to cause the latter relay to restore and effect the release of the amplifier network 171.

At this time the operator at the operator position 152 restores the common talk key K800 and replaces the receiver 757 upon its associated switchhook, whereby the answer relay R830 restores in order to effect the complete release of the equipment at the operator position 152, in the manner previously explained.

Individual call from the operator position to a telephone station

The operator at the operator position 152 may call any one of the telephone stations individually, such, for example, as the telephone station 1ZB. In order to initiate the present call, the operator at the operator position 152 removes the receiver 757 from the associated switchhook, thereby to operate the hook switch S760 in order to effect operation of the answer relay R830, all in the manner previously explained. The operator at the operator position 152 then operates the individual talk key K910, thereby to complete, at the contacts 912 thereof, an obvious circuit for energizing the winding of the call relay R550 in order to cause the latter relay to operate. Also, at the contacts 912 and 911 of the individual talk key K910, there is completed a circuit, including the conductor C821 and the contacts 821 of the common test key K820, for energizing the winding of the supply relay R860, thereby to cause the latter relay to operate. Upon operating, the supply relay R860 completes, at the contacts 861 and 862, a circuit for energizing the windings 767 and 768 of the repeater 765. The last-mentioned circuit extends from ground by way of the upper winding of the impedance element I874, the contacts 861, the windings 768 and 767 of the repeater 765, the contacts 862 and the lower winding of the impedance element I874 to battery.

Upon operating, the call relay R550 completes, at the contacts 555, an obvious circuit, including the resistor 513, for energizing the winding of the release relay R520, thereby to cause the latter relay to operate. Also the call relay R550 completes, at the contacts 556, an obvious circuit for energizing the winding of the cutoff relay R560, thereby to cause the latter relay to operate. Upon operating, the cutoff relay R560 interrupts, at the contacts 562, the normally completed connection between the hold conductor C581 and the ring start conductor C771, thereby positively to prevent operation of the pad switching relay R770 and the consequent loading of the repeater 700 in the operator position 152. Also the prevention of the application of ground potential to the ring start conductor C771 positively prevents the loading of the repeater 300 in the simulating impedance network 151 and the operation of the pad switching relays in the other line circuits 105, 106, etc. Also the release relay R520 completes, at the contacts 522, a circuit, including the contacts 555, 454 and 443, for energizing the upper winding of the pad switching relay R460, thereby to cause the latter relay to operate. Upon operating, the pad switching relay R460 completes, at the contacts 454, the previously traced circuit, including the simulating pad 410, for loading the repeater 400 in the line circuit 126. The loading of the repeater 400 in the line circuit 126 unbalances the B loop with respect to the A loop. However, no difficulty is caused by this unbalanced condition in view of the fact that no conference call is now in progress and the amplifier network 171 is not operating at this time. Furthermore, this unbalancing of the B loop conditions the amplifier network 171, whereby a balanced condition will be produced in the event a conference call is initiated during the progress of the individual call between the operator position 152 and the called telephone station 1ZB, in a manner more fully explained hereinafter.

Continuing now with the extension of the individual call from the operator position 152 to the called telephone station 1ZB, upon operating, the call relay R550 also completes, at the contacts 552 and 554, an operative connection between the repeater 765 at the operator position 152 and the repeater 640 in the adapter circuit 136. The above-mentioned connection extends from the condenser 622 by way of the winding 643 of the repeater 640, the contacts 631, 571 and 552, the contacts 913 of the individual talk key K910, C822, the contacts 822 of the common test key K820, the contacts 806 of the common ring key K805, the windings 768 and 767 of the repeater 765, the condenser 816, the contacts 808 of the common ring key K805, the contacts 825 of the common test key K820, C823, the contacts 916 of the individual talk key K910, the contacts 554, 572 and 634 and the winding 644 of the repeater 640 to the condenser 622.

At this time the operator at the operator position 152 operates and restores the common ring key K805. When the common ring key K805 is thus operated there is interrupted, at the contacts 806 and 808 thereof, the previously traced connection between the repeaters 765 and 640, and there is completed, at the contacts 807 and 809 thereof, a ringing circuit substantially identical to that previously traced for projecting ringing current to the repeater 640. Subsequently, when the common ring key K805 is restored there is interrupted, at the contacts 807 and 809, the above-mentioned circuit for projecting ringing current over the repeater 640, and there is recompleted, at the contacts 806 and 808 thereof, the above-traced operative connection between the repeater 765 and the repeater 640. The ringing current traversing the windings 643 and 644 of the repeater 640 induces a corresponding ringing voltage in the windings 641 and 642 thereof, whereby a corresponding ringing current traverses the previously traced connection including the trunk line 132 and the windings 653 and 654 of the repeater 650 in area Z. The ringing current traversing the windings 653 and 654 of the repeater 650 induces a corresponding ringing voltage in the windings 651 and 652 thereof, whereby a corresponding ringing current is projected over the previously traced connection, including the telephone line 122, extending to the called telephone station 1ZB in order to cause operation of the ringer at the last-mentioned station. When the person at the telephone station 1ZB answers the call by removing the receiver of the telephone instrument thereat from its associated switchhook the previously traced simplex circuit for energizing the winding of the simplex relay R620 is completed in order to cause the latter relay to operate. Upon operating, the simplex relay R620 completes, at the contacts 621, an obvious path for short-circuiting the condenser 622. Accordingly, at this time, an operative connection is completed between the operator position 152 and the telephone station 1ZB and the conversation therebetween may proceed.

During the progress of the individual call between the operator position 152 and the telephone station 1ZB, it is noted that the repeater 700 in the operator position 152, the repeater 300 in the simulating impedance network 151 and the repeaters in the various line circuits 101, 102, etc. are unloaded. However, the repeater 400 in the line circuit 126 is loaded by the previously traced circuit including the simulating pad 410, whereby the B loop is unbalanced with respect to the

A loop, as previously noted. However, this unbalance between the B loop and the A loop is productive of no difficulty in view of the fact that the amplifier network 171 is not operative at this time, no conference call being in progress.

Now assume that, during the progress of the present individual call between the operator position 152 and the telephone station 1ZB, a conference call is initiated at one of the other telephone stations, such, for example, as the telephone station 1XA. When the conference call is thus initiated the line circuit 105 individual to the telephone station 1XA operates, thereby to cause ground potential to be applied to the ring start conductor C771; whereby the pad switching relay R710 is operated in order to effect loading of the repeater 700 in the operator position 152, the repeater 300 in the simulating impedance network 151 is loaded and the repeater in each line circuit is loaded, all in the manner previously explained. At this point it is noted that the repeater 400 in the line circuit 126 has already been loaded due to the operation of the pad switching relay R460. Hence, at this time, the A loop and the B loop are again balanced and the amplifier network 171 is rendered operative in the manner previously explained. The persons at the other telephone stations 1YA, 1YB, etc., answer the conference call in response to the signaling of the stations mentioned, whereby a conference connection is completed which includes the calling telephone station 1XA and the various called telephone stations 1YA, 1YB, etc. Also the apparatus at the operator position 152 is controlled in order to indicate to the operator thereat that a conference call has been initiated and is now in progress. This indication to the operator at the operator position 152 is produced by the illumination of the individual call lamp corresponding to the line circuit 105 and the illumination of the various individual answer lamps corresponding to the line circuits 115, 116, etc.

At this time the operator at the operator position 152 may terminate the individual call extending to the called telephone station 1ZB and cause the operator position 152 and the called telephone station 1ZB to be included in the conference call. This may be accomplished by the operator at the operator position 152 by restoring the individual talk key K910 and by operating the common talk key K800. When the individual talk key K910 is restored there is interrupted, at the contacts 913 and 916 thereof, the previously traced connection between the repeater 765 and the repeater 640. Also, at the contacts 912 of the individual talk key K910, there is interrupted the previously traced multiple circuits for energizing the windings of the supply relay R860 and the call relay R550, thereby to cause the latter relays to restore. Upon restoring, the supply relay R860 interrupts, at the contacts 861 and 862, the previously traced operative connection between the impedance element 1874 and the repeater 765.

Upon restoring, the call relay R550 interrupts, at the contacts 555, the previously traced multiple circuits for energizing the winding of the release relay R520 and the upper winding of the pad switching relay R460, thereby to cause the latter relays to restore. Also the call relay R550 interrupts, at the contacts 556, the previously mentioned circuit for energizing the winding of the cutoff relay R560, thereby to cause the latter relay to restore shortly thereafter, the cutoff relay R560 being of the slow-to-release type. Fur-

ther the call relay R550 completes, at the contacts 551 and 553, the previously traced operative connection between the repeater 640 in the adapter circuit 136 and the repeater 400 in the line circuit 126, whereby the line relay R405 is retained operated. Upon restoring, the release relay R520 and the pad switching relay R460 effect operation of the hold relay R440. Upon restoring, the cutoff relay R560 completes, at the contacts 562, the previously mentioned connection between the hold conductor C581 and the ring start conductor C777, thereby to render the ultimate release of the line circuit 126 under the control of the last person at one of the telephone stations to replace the receiver of the telephone instrument thereat upon its associated switchhook, in the manner previously explained.

When the operator at the operator position 152 operates the common talk key K800 there is interrupted, at the contacts 802, the previously traced circuit for energizing the winding of the pad switching relay R770, thereby to cause the latter relay to restore. Upon restoring, the pad switching relay R770 interrupts, at the contacts 773 and 776, the previously traced circuit, including the simulating pad 710, for loading the repeater 769, and completes, at the contacts 774, 772, 774 and 775, the previously traced operative connection between the repeater 760 and the repeater 765. At this time the previously mentioned conference connection includes the operator position 152 and the telephone station 1ZB. The subsequent release of this conference connection, as well as the supervision thereof, at the operator position 152 are the same as previously described.

Now assume that the individual call connection is set up from the operator position 152 to the called telephone station 1ZB, in the manner previously explained, and that this connection is released in an ordinary manner. In order to release the individual call connection mentioned, the operator at the operator position 152 instructs the person at the telephone station 1ZB to replace the receiver of the telephone instrument thereat upon its associated switchhook. When the receiver of the telephone instrument at the telephone station 1ZB is replaced upon its associated switchhook the previously traced circuit for energizing the winding of the simplex relay R620 is interrupted, thereby to cause the latter relay to restore. The operator at the operator position 152 then restores the individual talk key K910, thereby to interrupt, at the contacts 913 and 916 thereof, the previously traced operative connection between the repeater 765 in the operator position 152 and the repeater 640 in the adapter circuit 136. Also, at the contacts 912 of the individual talk key K910, there is interrupted the previously traced multiple circuits for energizing the windings of the supply relay R860 and the call relay R550, thereby to cause the latter relays to restore. Upon restoring, the supply relay R860 interrupts, at the contacts 861 and 862, the previously traced operative connection between the impedance element 1874 and the repeater 765. Upon restoring, the call relay R550 interrupts, at the contacts 555, the previously traced multiple circuits for energizing the winding of the release relay R520 and the upper winding of the pad switching relay R460, thereby to cause the latter relays to restore. Upon restoring, the pad switching relay R460 interrupts, at the contacts 464, the previously traced circuit including the simulating pad 410, for loading the

repeater 400, whereupon the line relay R405 restores. Also, upon restoring, the call relay R550 effects the restoration of the cutoff relay R560 shortly thereafter, at which time the line circuit 126 is completely released. The operator at the operator position 152 then replaces the receiver 157 upon its associated switchhook, thereby to effect the release of the answer relay R830 in the manner previously explained. At this time the individual call extending between the operator position 152 and the telephone station 1ZB is completely released and the equipment utilized is rendered idle and available for further use.

Line lockout and test facilities

During normal operation of the telephone system any one of the telephone lines may develop a fault between the line conductors thereof, causing a conference call to be initiated. For example, assuming that a line fault appears between the line conductors of the telephone line 122 extending to the telephone station 1ZB, the previously traced circuit for energizing the winding of the simplex relay R620 is completed, thereby to cause the latter relay to operate. Upon operating, the simplex relay R620 effects operation of the line relay R405, the hold relay R440, the supervisory relay R610, the amplifier start relay R850, the call relay R880 and the alarm relay R870 and the illumination of the individual call lamp L932, all in the manner previously explained. This operation of the relays mentioned in the line circuit 126 effects the initiation of a conference call which is answered at the operator position 152 and the other telephone stations 1XA, 1XB, etc., in the manner previously explained; whereupon the answer relay R830 and the cutoff relay R840 operate in order to effect restoration of the alarm relay R870. At this time a conference connection is set up, including the operator position 152 and the various answering telephone stations 1XA, 1XB, etc., whereupon the operator at the operator position 152 observes that the conference call was initiated on the telephone line 122 due to the illumination of the individual call lamp L932, but learns that the call was not initiated at the telephone station 1ZB in view of the failure of any person thereat to converse over the conference circuit. The operator at the operator position 152 then concludes that the conference call was initiated due to a fault appearing between the line conductors of the telephone line 122 and advises the persons at the other telephone stations 1XA, 1XB, etc., accordingly. The operator at the operator position 152 then restores the common talk key K800 and operates the individual talk key K910 and the persons at the other telephone stations 1XA, 1XB, etc., replace the receivers of the telephone instruments thereat in order to effect the release of the conference connection, all in the manner previously explained. At this time an individual call connection is set up from the operator position 152 by way of the individual talk key K910 to the telephone line 122 extending to the telephone station 1ZB. The operator at the operator position 152 then operates the common key ring K805 and endeavors to operate the ringer at the telephone station 1ZB, in the manner previously explained. Finally the operator at the operator position 152 concludes that there is a fault between the line conductors of the telephone line 122 and that the telephone station 1ZB cannot be signaled. At this time the operator at the

operator position 152 operates the common line lockout key K930, thereby to complete a circuit, including the contacts 914 and the conductor C425, for energizing the lower winding of the lockout relay R540, thereby to cause the latter relay to operate. Upon operating, the lockout relay R540 completes, at the contacts 548, an obvious holding circuit, including the contacts 551, for energizing the lower winding thereof. Also the lockout relay R540 interrupts, at the contacts 541 and 544, the previously traced connection between the repeater 400 in the line circuit 126 and the repeater 640 in the adapter circuit 136. Further the lockout relay R540 completes, at the contacts 546, a multiple holding circuit for energizing the winding of the release relay R520 and the upper winding of the pad switching relay R460, the relays mentioned being operated incident to the operation of the call relay R550 when the individual talk key K910 was operated, as previously noted. Also the lockout relay R540 completes, at the contacts 547, a multiple holding circuit for energizing the winding of the cutoff relay R560, thereby to retain the latter relay in its operated position. Finally the lockout relay R540 completes, at the contacts 549, an obvious circuit for illuminating the individual line lockout lamp L819, thereby to indicate to the operator at the operator position 152 that the telephone line 122 extending to the telephone station 1ZB is locked out of service at this time.

The operator at the operator position 152 then restores the individual talk key K910, thereby to effect the restoration of the supply relay R860 and the call relay R550, in the manner previously explained. Upon restoring, the call relay R550 completes, at the contacts 551 and 553, a holding circuit for energizing the upper winding of the lockout relay R540, this circuit extending from ground by way of the contacts 545, 553, 572 and 634, the winding 644 of the repeater 640, the contacts 621 of the operated simplex relay R620, the winding 643 of the repeater 640, the contacts 636, 571, 551 and 542 and the upper winding of R540 to battery. Further the call relay R550 interrupts, at the contacts 557, the previously traced holding circuit for energizing the lower winding of the lockout relay R540; however, the latter relay remains in its operated position at this time due to the completed holding circuit for energizing the upper winding thereof traced above.

The pad switching relay R460 in the line circuit 126 is retained in its operated position as noted above, whereby the repeater 400 therein is retained loaded. The loading of the repeater 400 in the line circuit 126 unbalances the B loop with respect to the A loop; however, this unbalance is without effect at this time as the amplifier network 171 is not operative and no conference call is in progress. However, when a conference call is initiated the repeaters in the remainder of the line circuits are loaded, whereby the B loop and the A loop are again balanced, as previously explained.

After the telephone line 122 extending to the telephone station 1ZB, which is now locked out of service, has been placed in working order the previously traced simplex circuit for energizing the winding of the simplex relay R620 is interrupted, the last-mentioned circuit being interrupted when the line fault between the line conductors of the telephone line 122 is removed, whereby the last-mentioned relay restores. Upon

restoring, the simplex relay R620 interrupts, at the contacts 621, the previously traced holding circuit for energizing the upper winding of the lockout relay R540, thereby to cause the latter relay to restore shortly thereafter, the lockout relay R540 being of the slow-to-release type. Upon restoring, the lockout relay R540 prepares, at the contacts 541 and 544, points in the previously traced connection between the repeater 400 in the line circuit 126 and the repeater 640 in the adapter circuit 136; and interrupts, at the contacts 548, the previously traced multiple circuits for energizing the winding of the release relay R520 and the upper winding of the pad switching relay R460, thereby to cause the latter relays to restore. Upon restoring, the pad switching relay R460 interrupts, at the contacts 464, the previously traced circuit, including the simulating pad 410, for loading the repeater 400, whereupon the line relay R405 restores. Also the lockout relay R540 interrupts, at the contacts 547, the previously mentioned circuit for energizing the winding of the cutoff relay R560; and interrupts, at the contacts 549, the previously mentioned circuit for illuminating the individual line lockout lamp L819; thereby to indicate to the operator at the operator position 152 that the telephone line 122 extending to the telephone station 1ZB has again been placed in service. Shortly thereafter the cutoff relay R560 restores to re-complete, at the contacts 562, the previously mentioned connection between the hold conductor C581 and the ring start conductor C711. At this time the line circuit 126 is completely released and the telephone station 1ZB is now again placed in service.

At any time the operator at the operator position 152 may complete a connection between the test desk 161 and any one of the telephone lines 122 extending to a corresponding one of the telephone stations by operating the common test key K820 in conjunction with the individual talk key corresponding to the telephone line which is to be connected to the test desk 161. Assume that the test desk 161 is to be connected to the telephone line 122 extending to the telephone station 1ZB at this time. The operator at the operator position 152 operates the common test key K820 in conjunction with the individual talk key K910. When the individual talk key K910 is thus operated subsequent to the operation of the common test key K820, there is completed, at the contacts 915 thereof, a circuit, including the contacts 824 of the common test key K820 and the conductor C824, for energizing the winding of the test relay R830, thereby to cause the latter relay to operate. Also, at the contacts 912 of the individual talk key K910, there is completed the previously traced circuit for energizing the winding of the call relay R550, thereby to cause the latter relay to operate. Upon operating, the call relay R550 effects operation of the release relay R520, the pad switching relay R460 and the cutoff relay R560, all in the manner previously explained. Also the call relay R550 completes, at the contacts 552 and 554, the previously mentioned connection between the test desk 161 and the telephone line 122 extending to the telephone station 1ZB. The last-mentioned connection extends from the line conductor C661 of the trunk 660 by way of the contacts 823 of the common test key K820, C822, the contacts 913 of the individual talk key K910, the contacts 552, 571 and 632, one of the line conductors of the trunk line 132, the windings 653 and 654 of the repeater

650, the other line conductor of the trunk line 132, the contacts 635, 572 and 554, the contacts 916 of the individual talk key K910, C823 and the contacts 826 of the common test key K820 to the line conductor C662 of the trunk 660, the line conductors C661 and C662 of the trunk 660 extending to the test desk 161. Accordingly the test operator at the test desk 161 may perform certain tests over the above-traced connection, including the trunk line 132 extending to the repeater 650 in area Z, thereby to determine the condition of the trunk line 132, the repeater 650 and the connected telephone line 122 extending to the telephone station 12B.

In order to release the above-mentioned connection between the test desk 161 and the telephone line 122 extending to the telephone station 12B, the operator at the operator position 152 restores the individual talk key K910 and the common test key K820, thereby to interrupt the previously traced circuits for energizing the windings of the call relay R550 and the test relay R530, whereupon the latter relays restore. Upon restoring, the call relay R550 effects restoration of the release relay R520, the pad switching relay R460 and the cutoff relay R560, in the manner previously explained.

Also the repeaters in the various line circuits 105, 106, etc., may be tested with reference to the associated loops and the amplifier network 171. More particularly, the repeaters in the various line circuits 105, 106 and 115, 116, etc., should be tested in pairs in order to prevent unbalance of the loops extending to the amplifier network 171. For example, assuming that the repeaters in the line circuits 125 and 126 are to be tested, the testman inserts two corresponding plugs into the test jacks provided in the respective line circuits mentioned. One of the plugs is inserted into the test jacks J576 and J577 in the line circuit 126; and the other plug is inserted into the corresponding test jacks in the line circuit 125. When the plug is inserted into the jack J577 in the line circuit 126 an obvious circuit is completed for energizing the winding of the test relay R570, thereby to cause the latter relay to operate. Upon operating, the test relay R570 interrupts, at the contacts 571 and 572, further points in the previously traced connection between the repeater 400 in the line circuit 126 and the repeater 640 in the adapter circuit 136. Also the test relay R570 completes, at the contacts 573, an obvious circuit for energizing the winding of the cutoff relay R560, thereby to cause the latter relay to operate. Further the test relay R570 completes, at the contacts 575, an obvious circuit for energizing the winding of the amplifier start relay R850, thereby to cause the latter relay to operate and effect operation of the amplifier start slave relay R260 and the consequent operation of the amplifier network 171, in the manner previously explained. Also the test relay R570 completes, at the contacts 574, an obvious path for applying ground potential to the hold conductor C581, thereby to effect operation of the pad switching relay R460, whereupon the line relay R405 is operated in the manner previously explained.

Upon operating, the cutoff relay R560 interrupts, at the contacts 562, the previously mentioned connection between the hold conductor C581 and the ring start conductor C777, thereby to prevent operation of the other line circuits and the consequent signaling of the other telephone stations. Also the cutoff relay R560 com-

pletes, at the contacts 561, a circuit substantially identical to that previously traced and including the plug inserted into the jack J576 for energizing the winding of the ring cutoff relay R510, thereby to cause the latter relay to operate in the manner previously explained. Upon operating, the ring cutoff relay R510 effects operation of the answer relay R450, the restoration of the pad switching relay R460 and the operation of the hold relay R440, all in the manner previously explained. At this time an operative connection is completed between the test set and the repeater 400 in the line circuit 126.

In a similar manner, an operative connection is completed between the test set and the repeater in the line circuit 125. Accordingly the test set is operatively connected by way of the repeater 400 in the line circuit 126 and the B loop to the amplifier network 171 and by way of the repeater 400 in the line circuit 125 and the A loop to the amplifier network 171. Moreover, the repeater 300 in the simulating impedance network 151, the repeater 700 in the operator position 152 and the repeater in each of the other line circuits, excluding the repeaters in the line circuits 125 and 126, are unloaded at this time. Thus the testman may determine the performance of the repeater in the line circuit 125 and the repeater 400 in the line circuit 126.

30 After the repeaters mentioned have been tested the testman withdraws the plugs from the test jacks mentioned in the two line circuits 125 and 126. The test relay R570 and the line relay R405 in the line circuit 126 restore, in an obvious manner. The restoration of the test relay R570 effects the restoration of the cutoff relay R560 shortly thereafter, in an obvious manner, while the restoration of the line relay R405 effects operation of the release relay R560 and the pad switching relay R460 and the subsequent restoration of the hold relay R440, all in the manner previously explained. Upon restoring, the hold relay R440 effects restoration of the answer relay R450, the release relay R520 and the pad switching relay R460, all in the manner previously explained. At this time the line circuit 126 is completely released and is in readiness for further use.

Further the repeaters in the various line circuits 105, 106, etc., may be tested without reference to the associated loops and the amplifier network 171. More particularly, the repeaters in the various line circuits 105, 106 and 115, 116, etc., should be tested in pairs in order to prevent unbalance of the loops extending to the amplifier network 171. For example, assuming that the repeaters in the line circuits 125 and 126 are to be tested, the testman inserts two corresponding plugs into the test jacks provided in the respective line circuits mentioned. One of the plugs is inserted into the test jack J420 in the line circuit 126; and the other plug is inserted into the corresponding test jack in the line circuit 125. When the plug is inserted into the test jack J420 in the line circuit 126 an obvious path is completed at the contacts 421 thereof in the B loop; and there is interrupted, at the contacts 422 and 423 thereof, the previously traced path including the windings 401 and 402 of the repeater 400 in B loop. Also the plug inserted into the test jack J420 applies ground potential to the sleeve 424 thereof, thereby to complete an obvious circuit, including the conductor C428, for energizing the lower winding of the lockout relay R540 in order to cause the latter relay to operate.

Upon operating the lockout relay R540 interrupts at the contacts 541 and 544 further points in the previously traced connection between the repeater 400 in the line circuit 126 and the repeater 640 in the adapter circuit 136. Further the lockout relay R540 effects operation of the release relay R520, the pad switching relay R460 and the cutoff relay R560, all in the manner previously explained. Upon operating the pad switching relay R460 completes, at the contacts 464, the previously traced circuit, including the simulating pad 410, for loading the repeater 400, whereupon the line relay R405 operates. Finally, at the tip and the ring of the test jack J420, an obvious connection is completed between the test set and the windings 401 and 402 of the repeater 400. In a similar manner, an operative connection is completed between the test set and the repeater in the line circuit 125. Accordingly, the test set is operatively connected to the repeater 400 in the line circuit 126 and to the repeater in the line circuit 125. Moreover, the repeater 400 in the line circuit 126 and the repeater in the line circuit 125 are disconnected, respectively from the B loop and the A loop, whereby the two loops are balanced with respect to the amplifier network 171, in the manner previously explained. Thus the testman may determine the performance of the repeater in the line circuit 125 and the repeater 400 in the line circuit 126.

After the repeaters mentioned have been tested the testman withdraws the plugs from the test jacks mentioned in the two line circuits 125 and 126, whereupon the repeater in the line circuit 125 and the repeater 400 in the line circuit 126 are again respectively included in the A loop and in the B loop. More particularly, when the plug is withdrawn from the jack J420 there is interrupted, at the contacts 421 thereof, the previously mentioned shunt path in the B loop; and there is completed, at the contacts 422 and 423 thereof, the previously traced path for connecting the windings 401 and 402 of the repeater 400 in the B loop. Also when the plug is withdrawn from the test jack J420 the previously traced circuit for energizing the winding of the lockout relay R540 is interrupted, thereby to cause the latter relay to restore and effect the restoration of the release relay R520, the pad switching relay R460, the line relay R405 and the cutoff relay R560, all in the manner previously explained. At this time the line circuit 126 is completely released and is in readiness for further use.

The adapter circuits

Again referring to the adapter circuit 136 it is pointed out that, in the telephone system, the ringing current and the voice frequency current traversing the trunk line 132 extending between the repeater 640 in the central office and the repeater 650 in the area Z are conducted by way of a loop connection including the two line conductors of the trunk line 132 in series. On the other hand, the direct current traversing the trunk 132 which is utilized for energizing the winding of the simplex relay R620 and for operating the transmitter at the telephone station 1ZB is conducted by way of a simplex connection including the two line conductors of the trunk line 132 in parallel. Accordingly, in the adapter circuit 136, the resistance of the simplex connection, including the trunk line 132, to the direct current for operating the transmitter at the telephone station 1ZB is only one-fourth of what a loop con-

nection including the trunk line 132 would be. This arrangement positively insures the supply of adequate current for operating the transmitter at the telephone station 1ZB and for energizing the winding of the simplex relay R620.

Also it is noted that the impedance 656 and the condenser 655 comprise a noise filter which is effective to prevent stray currents induced in the simplex circuit, including the trunk line 132, from being conducted into the loop circuit extending from the windings 651 and 652 of the repeater 650 over the telephone line 122 to the telephone station 1ZB.

Conclusions

From the foregoing it is apparent that a telephone system is provided, which comprises an improved arrangement for setting up conference calls including an operator position disposed in a central office and a plurality of telephone stations disposed in a number of different areas remote from the central office.

While one embodiment of the invention has been disclosed it will be understood that various modifications may be made therein, which are within the true spirit and scope of the invention.

What is claimed is:

1. In a telephone system, two groups of stations, two signal channels individually connected to the stations in said two groups, each of said stations including transmitter means for originating a signal upon the connected channel and receiver means for reproducing an amplified signal delivered to the connected channel, an amplifier operative to deliver amplified signals to both of said channels and including an input circuit, and means for transmitting a signal originating upon either of said channels to said input circuit and for preventing an amplified signal delivered to both of said channels from being transmitted to said input circuit.
2. In a telephone system, two groups of telephone stations, two balanced signal channels individually connected to the stations in said two groups, each of said stations including transmitter means for originating a signal upon the connected channel and receiver means for reproducing an amplified signal delivered to the connected channel, an amplifier operative to deliver amplified signals to both of said channels and including an input circuit, and coupling means for transmitting a signal originating upon either of said channels to said input circuit and for preventing an amplified signal delivered to both of said channels from being transmitted to said input circuit.
3. In a telephone system, two groups of telephone stations, two groups of line circuits individually connected to said two groups of stations by two groups of telephone lines, two signal channels individually connected to the line circuits in said two groups, each of said stations including transmitter means for originating a signal upon the connected channel and receiver means for reproducing an amplified signal delivered to the connected channel, an amplifier operative to deliver amplified signals to both of said channels and including an input circuit, and means for transmitting a signal originating upon either of said channels to said input circuit and for preventing an amplified signal delivered to both of said channels from being transmitted to said input circuit.
4. In a telephone system, two groups of telephone stations, two groups of line circuits individ-

ividually connected to said two groups of stations by two groups of telephone lines, two signal channels individually connecting the line circuits in said two groups in series, each of said stations including transmitter means for originating a signal upon the connected channel and receiver means for reproducing an amplified signal delivered to the connected channel, an amplifier operative to deliver amplified signals to both of said channels and including an input circuit, and means for transmitting a signal originating upon either of said channels to said input circuit and for preventing an amplified signal delivered to both of said channels from being transmitted to said input circuit.

5. In a telephone system, two groups of repeaters, each of said repeaters including a primary winding and a secondary winding, two groups of telephone stations, two groups of telephone lines individually connecting said two groups of stations to the secondary windings of said two groups of repeaters, two signal channels individually connecting the primary windings of said two groups of repeaters in series, each of said stations including transmitter means for originating a signal upon the connected channel and receiver means for reproducing an amplified signal delivered to the connected channel, an amplifier operative to deliver amplified signals to both of said channels and including an input circuit, and means for transmitting a signal originating upon either of said channels to said input circuit and for preventing an amplified signal delivered to both of said channels from being transmitted to said input circuit.

6. In a telephone system, two groups of stations, two groups of coupling devices individually associated with the stations in said two groups, two balanced signal channels individually associated with said two groups of coupling devices, means responsive to the initiation of a call at any calling station for causing the associated coupling device to couple said calling station to the associated channel and for causing the other coupling devices to couple corresponding artificial loads to the associated channels, thereby to maintain balanced said two channels, means responsive to the answering of the call at any called station for causing the associated coupling device to uncouple the corresponding artificial load from the associated channel and to couple said called station thereto, thereby to maintain balanced said two channels, each of said stations including transmitter means for originating a signal upon the coupled channel and receiver means for reproducing an amplified signal delivered to the coupled channel, an amplifier operative to deliver amplified signals to both of said channels and including an input circuit, and coupling means for transmitting a signal originating upon either of said channels to said input circuit and for preventing an amplified signal delivered to both of said channels from being transmitted to said input circuit.

7. In a telephone system, two groups of stations, two groups of coupling devices individually associated with the stations in said two groups, two balanced signal channels individually associated with said two groups of coupling devices, means responsive to the initiation of a call at any calling station for causing the associated coupling device to couple said calling station to the associated channel and for causing the other coupling devices to couple corresponding artificial loads to the associated channels, thereby to main-

tain balanced said two channels, means responsive to the answering of the call at any called station for causing the associated coupling device to uncouple the corresponding artificial load from the associated channel and to couple said called station thereto, thereby to maintain balanced said two channels, means responsive to the subsequent release of the call at any station for causing the associated coupling device to uncouple the station from the associated channel and to recouple the corresponding artificial load thereto, thereby to maintain balanced said two channels, each of said stations including transmitter means for originating a signal upon the coupled channel and receiver means for reproducing an amplified signal delivered to the coupled channel, an amplifier operative to deliver amplified signals to both of said channels and including an input circuit, and coupling means for transmitting a signal originating upon either of said channels to said input circuit and for preventing an amplified signal delivered to both of said channels from being transmitted to said input circuit.

8. In a telephone system, two groups of stations, two groups of coupling devices individually associated with the stations in said two groups, two balanced signal channels individually associated with said two groups of coupling devices, means responsive to the initiation of a call at any calling station for causing the associated coupling device to couple said calling station to the associated channel and for causing the other coupling devices to couple corresponding artificial loads to the associated channels, thereby to maintain balanced said two channels, means responsive to the answering of the call at any called station for causing the associated coupling device to uncouple the corresponding artificial load from the associated channel and to couple said called station thereto, thereby to maintain balanced said two channels, means responsive to the subsequent release of the call at any station for causing the associated coupling device to uncouple the station from the associated channel and to recouple the corresponding artificial load thereto, thereby to maintain balanced said two channels, means responsive to the ultimate release of the call at the last of said stations for causing the associated coupling device to uncouple the station from the associated channel and for causing the other coupling devices to uncouple the corresponding artificial loads from the associated channels, thereby to maintain balanced said two channels, each of said stations including transmitter means for originating a signal upon the coupled channel and receiver means for reproducing an amplified signal delivered to the coupled channel, an amplifier operative to deliver amplified signals to both of said channels and including an input circuit, and coupling means for transmitting a signal originating upon either of said channels to said input circuit and for preventing an amplified signal delivered to both of said channels from being transmitted to said input circuit.

9. In a telephone system, two groups of stations, two groups of coupling devices individually associated with the stations in said two groups, two balanced signal channels individually associated with said two groups of coupling devices, means responsive to the initiation of a call at any calling station for causing the associated coupling device to couple said calling station to the associated channel and for causing the other coupling

70

75

devices to couple corresponding artificial loads to the associated channels, thereby to maintain balanced said two channels, means responsive to the answering of the call at any called station for causing the associated coupling device to uncouple the corresponding artificial load from the associated channel and to couple said called station thereto, thereby to maintain balanced said two channels, means responsive to the subsequent release of the call at any station for causing the associated coupling device to uncouple the station from the associated channel and to recouple the corresponding artificial load thereto, thereby to maintain balanced said two channels, means responsive to the subsequent reanswering of the call at any station for causing the associated coupling device again to uncouple the corresponding artificial load from the associated channel and again to recouple the station thereto, thereby to maintain balanced said two channels, each of said stations including transmitter means for originating a signal upon the coupled channel and receiver means for reproducing an amplified signal delivered to the coupled channel, an amplifier operative to deliver amplified signals to both of said channels and including an input circuit, and coupling means for transmitting a signal originating upon either of said channels to said input circuit and for preventing an amplified signal delivered to both of said channels from being transmitted to said input circuit.

10. In a telephone system, two groups of stations, two groups of lines individually extending to the stations in said two groups, two groups of line pads individually connected to the lines in said two groups, each line and the connected line pad in one of said groups being paired and balanced with respect to a corresponding line and the connected line pad in the other of said groups, two groups of coupling devices individually associated with the line pads in said two groups, two balanced signal channels individually associated with said two groups of coupling devices, means responsive to the initiation of a call at any calling station for causing the associated coupling device to couple the associated line and the connected line pad to the associated channel and for causing the other coupling devices to couple corresponding artificial loads to the associated channels, thereby to maintain balanced said two channels, means responsive to the answering of the call at any called station for causing the associated coupling device to uncouple the corresponding artificial load from the associated channel and to couple the associated line and the connected line pad thereto, thereby to maintain balanced said two channels, each of said stations including transmitter means for originating a signal upon the coupled channel and receiver means for reproducing an amplified signal delivered to the coupled channel, an amplifier operative to deliver amplified signals to both of said channels and including an input circuit, and coupling means for transmitting a signal originating upon either of said channels to said input circuit and for preventing an amplified signal delivered to both of said channels from being transmitted to said input circuit.

11. In a telephone system, two groups of stations, two groups of lines individually extending to the stations in said two groups, two groups of line pads individually connected to the lines in said two groups, each line and the connected line pad in one of said groups being paired and balanced with respect to a corresponding line and

- the connected line pad in the other of said groups, two groups of coupling devices individually associated with the line pads in said two groups, two groups of simulating pads individually associated with the lines in said two groups, each of said simulating pads simulating the associated line and the connected line pad, two balanced signal channels individually associated with said two groups of coupling devices, means responsive to the initiation of a call at any calling station for causing the associated coupling device to couple the associated line and the connected line pad to the associated channel and for causing the other coupling devices to couple the associated simulating pads to the associated channels, thereby to maintain balanced said two channels, means responsive to the answering of the call at any called station for causing the associated coupling device to uncouple the associated simulating pad from the associated channel and to couple the associated line and the connected line pad thereto, thereby to maintain balanced said two channels, each of said stations including transmitter means for originating a signal upon the coupled channel and receiver means for reproducing an amplified signal delivered to the coupled channel, an amplifier operative to deliver amplified signals to both of said channels and including an input circuit, and coupling means for transmitting a signal originating upon either of said channels to said input circuit and for preventing an amplified signal delivered to both of said channels from being transmitted to said input circuit.
15. In a telephone system, first and second groups of stations, an operator position, a simulating network, a first signal channel connected to the stations in said first group and to said operator position, a second signal channel connected to the stations in said second group and to said simulating network, each of said stations and said operator position including transmitter means for originating a signal upon the connected channel and receiver means for reproducing an amplified signal delivered to the connected channel, an amplifier operative to deliver amplified signals to both of said channels and including an input circuit, and means for transmitting a signal originating upon either of said channels to said input circuit and for preventing an amplified signal delivered to both of said channels from being transmitted to said input circuit.
20. In a telephone system, first and second groups of stations, an operator position, a simulating network, a first signal channel connected to the stations in said first group and to said operator position, a second signal channel connected to the stations in said second group and to said simulating network, each of said stations and said operator position including transmitter means for originating a signal upon the connected channel and receiver means for reproducing an amplified signal delivered to the connected channel, an amplifier operative to deliver amplified signals to both of said channels and including an input circuit, and coupling means for transmitting a signal originating upon either of said channels to said input circuit and for preventing an amplified signal delivered to both of said channels from being transmitted to said input circuit.
25. In a telephone system, first and second groups of stations, an operator position, a simulating network, a first signal channel connected to the stations in said first group and to said operator position, a second signal channel connected to the stations in said second group and to said simulating network, each of said stations and said operator position including transmitter means for originating a signal upon the connected channel and receiver means for reproducing an amplified signal delivered to the connected channel, an amplifier operative to deliver amplified signals to both of said channels and including an input circuit, and coupling means for transmitting a signal originating upon either of said channels to said input circuit and for preventing an amplified signal delivered to both of said channels from being transmitted to said input circuit.
30. In a telephone system, two groups of stations, two groups of first coupling devices individually associated with the stations in said two groups, an operator position, a second coupling device associated with said operator position, a simulating network, a third coupling device associated with said simulating network, a first signal channel associated with one group of said first coupling devices and said second coupling device, a second signal channel associated with the other group of said first coupling devices and said third coupling device, said first and second signal channels being balanced with respect to each other, means responsive to the initiation of a call at any calling station for causing the associated first coupling device to couple said calling station to the associated channel and for causing the other first coupling devices and said second and third coupling devices to couple corresponding artificial loads to the associated channels, thereby to maintain balanced said two channels, means responsive to the answering of the call at any called station for causing the associated first

coupling device to uncouple the corresponding artificial load from the associated channel and to couple said called station thereto, thereby to maintain balanced said two channels, means responsive to the answering of the call at said operator position for causing said second coupling device to uncouple the corresponding artificial load from said first channel and to couple said operator position thereto, thereby to maintain balanced said two channels, each of said stations and said operator position including transmitter means for originating a signal upon the coupled channel and receiver means for reproducing an amplified signal delivered to the coupled channel, an amplifier operative to deliver amplified signals to both of said channels and including an input circuit, and coupling means for transmitting a signal originating upon either of said channels to said input circuit and for preventing an amplified signal delivered to both of said channels from being transmitted to said input circuit.

14. In a telephone system, two groups of stations, two groups of first coupling devices individually associated with the stations in said two groups, an operator position, a second coupling device associated with said operator position, a simulating network, a third coupling device associated with said simulating network, a first signal channel associated with one group of said first coupling devices and said second coupling device, a second signal channel associated with the other group of said first coupling devices and said third coupling device, said first and second signal channels being balanced with respect to each other, means responsive to the initiation of a call at said operator position for causing said second coupling device to couple said operator position to said first channel and for causing said first coupling devices and said third coupling device to couple corresponding artificial loads to the associated channels, thereby to maintain balanced said two channels, means responsive to the answering of the call at any called station for causing the associated first coupling device to uncouple the corresponding artificial load from the associated channel and to couple said called station thereto, thereby to maintain balanced said two channels, each of said stations and said operator position including transmitter means for originating a signal upon the coupled channel and receiver means for reproducing an amplified signal delivered to the coupled channel, an amplifier operative to deliver amplified signals to both of said channels and including an input circuit, and coupling means for transmitting a signal originating upon either of said channels to said input circuit and for preventing an amplified signal delivered to both of said channels from being transmitted to said input circuit.

15. In a telephone system, two groups of stations, two groups of first coupling devices individually associated with the stations in said two groups, an operator position, a second coupling device associated with said operator position, a simulating network, a third coupling device associated with said simulating network, a first signal channel associated with one group of said first coupling devices and said second coupling device, a second signal channel associated with the other group of said first coupling devices and said third coupling device, said first and second signal channels being balanced with respect to each other, means controllable from said operator position for locking any one of said stations out of service.

and for causing the associated first coupling device to couple a corresponding artificial load to the associated channel, thereby to unbalance said two channels, means responsive to the initiation of a call at any calling station in service for causing the associated first coupling device to couple said calling station to the associated channel and for causing the other coupling devices associated with stations in service and said second and third coupling devices to couple corresponding artificial loads to the associated channels, thereby again to balance said two channels, means responsive to the answering of the call at any called station in service for causing the associated first coupling device to uncouple the corresponding artificial load from the associated channel and to couple said called station thereto, thereby to maintain balanced said two channels, means responsive to the answering of the call at said operator position for causing said second coupling device to uncouple the corresponding artificial load from said first channel and to couple said operator position thereto, thereby to maintain balanced said two channels, each of said stations and said operator position including transmitter means for originating a signal upon the coupled channel and receiver means for reproducing an amplified signal delivered to the coupled channel, an amplifier operative to deliver amplified signals to both of said channels and including an input circuit, and coupling means for transmitting a signal originating upon either of said channels to said input circuit and for preventing an amplified signal delivered to both of said channels from being transmitted to said input circuit.

16. In a telephone system, two groups of stations, two groups of first coupling devices individually associated with the stations in said two groups, an operator position, a second coupling device associated with said operator position, a simulating network, a third coupling device associated with said simulating network, a first signal channel associated with one group of said first coupling devices and said second coupling device, a second signal channel associated with the other group of said first coupling devices and said third coupling device, said first and second signal channels being balanced with respect to each other, means controllable from said operator position for locking any one of said stations out of service and for causing the associated first coupling device to couple a corresponding artificial load to the associated channel, thereby to unbalance said two channels, means responsive to the initiation of a call at said operator position for causing said second coupling device to couple said operator position to said first channel and for causing said first coupling devices associated with stations in service and said third coupling device to couple corresponding artificial loads to the associated channels, thereby again to balance said two channels, means responsive to the answering of the call at any called station in service for causing the associated first coupling device to uncouple the corresponding artificial load from the associated channel and to couple said called station thereto, thereby to maintain balanced said two channels, each of said stations and said operator position including transmitter means for originating a signal upon the coupled channel and receiver means for reproducing an amplified signal delivered to the coupled channel, an amplifier operative to deliver amplified signals to both of said channels and including an input circuit, and coupling means for transmitting a signal originating upon either of said channels to said input circuit and for preventing an amplified signal delivered to both of said channels from being transmitted to said input circuit.

signal originating upon either of said channels to said input circuit and for preventing an amplified signal delivered to both of said channels from being transmitted to said input circuit.

17. In a telephone system, first and second groups of stations, first and second groups of coupling devices individually connected to the stations in said first and second groups, first and second signal channels respectively connected to said first and second groups of coupling devices, each of said stations including transmitter means for originating a signal upon the coupled channel and receiver means for reproducing an amplified signal delivered to the coupled channel, an amplifier operative to deliver amplified signals to both of said channels and including an input circuit, and means for transmitting a signal originating upon either of said channels to said input circuit and for preventing an amplified signal delivered to both of said channels from being transmitted to said input circuit.

18. In a telephone system, first and second groups of stations, first and second groups of coupling devices individually connected to the stations in said first and second groups, first and second booster transformers respectively connected to said first and second groups of coupling devices, first and second signal channels respectively connected to said first and second booster transformers, each of said stations including transmitter means for originating a signal upon the coupled channel and receiver means for reproducing an amplified signal delivered to the coupled channel, an amplifier operative to deliver amplified signals to both of said channels and including an input circuit, and means for transmitting a signal originating upon either of said channels to said input circuit and for preventing an amplified signal delivered to both of said channels from being transmitted to said input circuit.

19. In a telephone system, first and second groups of stations, first and second groups of coupling devices, first and second groups of simplex circuits individually connecting the stations in said first and second groups to the coupling devices in said first and second groups, first and second signal channels respectively connected to said first and second groups of coupling devices, each of said stations including transmitter means for originating a signal upon the coupled channel and receiver means for reproducing an amplified signal delivered to the coupled channel, an amplifier operative to deliver amplified signals to both of said channels and including an input circuit, and means for transmitting a signal originating upon either of said channels to said input circuit and for preventing an amplified signal delivered to both of said channels from being transmitted to said input circuit.

20. In a telephone system, first and second groups of stations, first and second groups of coupling devices individually connected to the stations in said first and second groups, third and fourth groups of stations, third and fourth groups of coupling devices individually connected to the stations in said third and fourth groups, first and second booster transformers respectively connected to said third and fourth groups of coupling devices, first and second signal channels respectively connected to said first and second groups of coupling devices and to said first and second booster transformers, each of said stations including transmitter means for originating a signal upon the coupled channel and receiver means for reproducing an amplified signal delivered to

the coupled channel, an amplifier operative to deliver amplified signals to both of said channels and including an input circuit, and means for transmitting a signal originating upon either of said channels to said input circuit and for preventing an amplified signal delivered to both of said channels from being transmitted to said input circuit.

21. In a telephone system, first and second groups of stations, first and second groups of coupling devices individually connected to the stations in said first and second groups, third and fourth groups of stations, third and fourth groups of coupling devices, first and second groups of simplex circuits individually connecting the stations in said third and fourth groups to the coupling devices in said third and fourth groups, first and second booster transformers respectively connected to said first and second groups of coupling devices, first and second signal channels respectively connected to said first and second booster transformers and to said third and fourth groups of coupling devices, each of said stations including transmitter means for originating a signal upon the coupled channel and receiver means for reproducing an amplified signal delivered to the coupled channel, an amplifier operative to deliver amplified signals to both of said channels and including an input circuit, and means for transmitting a signal originating upon either of said channels to said input circuit and for preventing an amplified signal delivered to both of said channels from being transmitted to said input circuit.

22. In a telephone system, first and second groups of stations, first and second groups of coupling devices individually connected to the stations in said first and second groups, third and fourth groups of stations, third and fourth groups of coupling devices, first and second groups of simplex circuits individually connecting the stations in said third and fourth groups to the coupling devices in said third and fourth groups, first and second signal channels respectively connected to said first and third and to said second and fourth groups of coupling devices, each of said stations including transmitter means for originating a signal upon the coupled channel and receiver means for reproducing an amplified signal delivered to the coupled channel, an amplifier operative to deliver amplified signals to both of said channels and including an input circuit, and means for transmitting a signal originating upon either of said channels to said input circuit and for preventing an amplified signal delivered to both of said channels from being transmitted to said input circuit.

23. In a conference telephone system, a plurality of stations, a plurality of lines individually extending to said stations, an amplifier network, means responsive to the initiation of a call at any calling station for rendering operative said amplifier network and for connecting the associated line to said amplifier network and for projecting ringing current over the other lines, and means responsive to the answering of the call at any called station for maintaining operative said amplifier network and for connecting the associated line to said amplifier network and for arresting the projection of ringing current over the associated line.

24. In a conference telephone system, a plurality of stations, a plurality of lines individually extending to said stations, a plurality of coupling devices individual to said lines, an amplifier net-

work, means responsive to the initiation of a call at any calling station for rendering operative said amplifier network and for causing the associated coupling device to couple the associated line to said amplifier network and for causing the other coupling devices to couple artificial loads to said amplifier network, and means responsive to the answering of the call at any called station for maintaining operative said amplifier network and for causing the associated coupling device to uncouple the artificial load from said amplifier network and to couple the associated line thereto.

25. In a conference telephone system, a plurality of stations, a plurality of lines individually extending to said stations, a plurality of repeaters individual to said lines, a plurality of simulating pads individual to said lines, an amplifier network connected to said repeaters, means responsive to the initiation of a call at any calling stations for completing a connection from said calling station by way of the associated line to the associated repeater and for completing connections between the other repeaters and the associated simulating pads, and means responsive to the answering of the call at any called station for interrupting the connection between the associated repeater and the associated simulating pad and for completing a connection from said called station by way of the associated line to the associated repeater.

26. In a conference telephone system, a plurality of stations, a plurality of lines individually extending to said stations, an operator position, an amplifier network, means responsive to the initiation of a call at any calling station for rendering operative said amplifier network and for connecting the associated line to said amplifier network and for transmitting a call signal individual to said calling station to said operator position, means responsive to the answering of the call at any called station for maintaining operative said amplifier network and for connecting the associated line to said amplifier network and for transmitting an answer signal individual to said called station to said operator position, and means controllable from said operator position for connecting said operator position to said amplifier network.

27. In a conference telephone system, a plurality of stations, a plurality of lines individually extending to said stations, an operator position, an amplifier network, means responsive to the initiation of a call at any calling station for rendering operative said amplifier network and for connecting the associated line to said amplifier network and for transmitting a call signal individual to said calling station to said operator position and for projecting ringing current over the other lines, means responsive to the answering of the call at any called station for maintaining operative said amplifier network and for connecting the associated line to said amplifier network and for transmitting an answer signal individual to said called station to said operator position and for arresting the projection of ringing current over the associated line, and means controllable from said operator position for connecting said operator position to said amplifier network.

28. In a conference telephone system, a plurality of stations, a plurality of lines individually extending to said stations, an operator position, an amplifier network, a plurality of first coupling devices individual to said lines, a second

coupling device individual to said operator position, means responsive to the initiation of a call at any calling station for rendering operative said amplifier network and for causing the associated coupling device to couple the associated line to said amplifier network and for causing the other first coupling device and said second coupling device to couple artificial loads to said amplifier network, means responsive to the answering of the call at any called station for maintaining operative said amplifier network and for causing the associated first coupling device to uncouple the artificial load from said amplifier network and to couple the associated line thereto, and means controllable from said operator position for causing said second coupling device to uncouple the artificial load from said amplifier network and to couple said operator position thereto.

29. In a conference telephone system, a plurality of stations, an operator position, a conference network, means responsive to the initiation of a call at any calling station for connecting said calling station to said conference network and for transmitting a call signal individual to said calling station to said operator position, means responsive to the answering of the call at any called station for connecting said called station to said conference network and for transmitting an answer signal individual to said called station to said operator position, and means controllable from said operator position for connecting said operator position to said conference network.

30. In a conference telephone system, a plurality of stations, a plurality of lines individually extending to said stations, an operator position, a conference network, means responsive to the initiation of a call at any calling station for connecting the associated line to said conference network and for transmitting a call signal individual to said calling station to said operator position and for projecting ringing current over at least some of the other lines extending to called stations, means responsive to the answering of the call at any called station for connecting the associated line to said conference network and for transmitting an answer signal individual to said called station to said operator position and for arresting the projection of ringing current over the associated line, and means controllable from said operator position for connecting said operator position to said conference network.

31. In a conference telephone system, a plurality of stations, a plurality of lines individually extending to said stations, an operator position, a conference network, means controllable from said operator position for preselecting any combination of said stations as called stations, means responsive to the initiation of a call at any calling station for connecting the associated line to said conference network and for projecting ringing current over each line extending to a station preselected as a called station, means responsive to the answering of the call at any called station for connecting the associated line to said conference network and for arresting the projection of ringing current over the associated line, and means controllable from said operator position for connecting said operator position to said conference network.

32. In a conference telephone system, a plurality of stations, a plurality of lines individually extending to said stations, an operator position,

circuits individually associated with said lines, each of said line circuits including a ring relay, said operator position including a plurality of select keys individually associated with said line circuits, each of said select keys being controllable to block operation of the ring relay in the associated line circuit, a conference network, means controllable from said operator position for connecting said operator position to said conference network and for operating the unblocked ring relays in the line circuits, means selectively controllable from said operator position for operating the blocked ring relay in any line circuit, means responsive to the operation of the ring relay in any line circuit for projecting ringing current over the associated line extending to a called station, and means responsive to the answering of the call at any called station for connecting the associated line to said conference network and for restoring the ring relay in the associated line circuit.

40. In a conference telephone system, three or more stations, a conference network, means responsive to the initiation of a call at any one of said stations for connecting said one station to said conference network and for extending calls to the other of said stations, and means responsive to the answering of a call at any other of said stations for connecting said other station to said conference network.

41. In a conference telephone system, three or more stations, a conference network, means responsive to the initiation of a call at any one of said stations for connecting said one station to said conference network and for extending calls to the other of said stations, means responsive to the answering of a call at any other of said stations for connecting said other station to said

conference network, and means for holding said conference network until each station connected thereto has released.

42. In a conference telephone system, three or more stations, a conference network, means responsive to an off-hook operation at any one of said stations for connecting said one station to said conference network and for extending calls to the other of said stations, and means responsive to the answering of a call at any other of said stations for connecting said other station to said conference network.

43. In a conference telephone system, a plurality of stations, a conference network, presettable means for selecting different ones of said stations as a called group, means controllable from any calling one of said stations for connecting said calling station to said conference network and for extending calls to the ones of said stations preselected as a called group, and means responsive to the answering of a call at any called station for connecting said called station to said conference network.

44. In a conference telephone system, a plurality of stations, a conference network, presettable means for selecting different ones of said stations as a called group, means responsive to the initiation of a call at any calling one of said stations for connecting said calling station to said conference network, means responsive to the connection of said calling station to said conference network for extending calls to the ones of said stations preselected as a called group, and means responsive to the answering of a call at any called station for connecting said called station to said conference network.

THOMAS F. CROCKER.
HOWARD H. SMITH.
